UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC, INC., A CORPORATION OF DELAWARE.

TELEPHONE-EXCHANGE SYSTEM.

Application filed October 20, 1906, Serial No. 339,833. Renewed August 28, 1916. Serial No. 117,067.

To all whom it may concern:

Be it known that I, TALBOT G. MARTIN, a citizen of the United States of America, and resident of Chicago, Cook County, Illinois, have invented a certain new and useful Improvement in Telephone-Exchange Systems, of which the following is a specification.

My invention relates to automatic or semi-automatic telephone exchange systems in general, but more particularly to automatic or semi-automatic exchanges in which the automatic trunking and connecting is accomplished by switches operated on the step-by-step principle, and especially to telephone systems in which provision is made for giving service between automatic and manual subscribers.

Generally stated the object of my invention is, therefore, the provision of an improved and highly efficient telephone exchange system.

Special objects of my invention are the provision of improved means for giving service between automatic and manual subscribers; the provision of improved means whereby an automatic subscriber may be called by either an automatic or a manual subscriber, and whereby a manual subscriber may be called by either an automatic or a manual subscriber, a calling automatic subscriber always obtaining the connection automatically, and a calling manual subscriber always obtaining the connection manually; the provision of improved means whereby called lines, whether automatic or manual, are made busy and protected against seizure by either automatic or manual subscribers, and whereby calling lines are also made busy, whether automatic or manual, and protected against seizure by either automatic or manual subscribers; the provision of improved means for trunking between main or central exchange stations, or between main and sub-central stations, according to the growth and size of the system; and the provision of certain details and features of improvement and novel circuits and combinations tending to increase the general efficiency and serviceability of a telephone exchange system of this particular character, as well as systems in general.

To the foregoing and other useful ends, my invention consists in matters hereinafter set forth and claimed.

The selectors and connectors employed in the system are of the general type disclosed in United States Letters Patent Nos. 815,321 and 815,176 both issued March 13, 1906, to Keith, Erickson & Erickson.

In the accompanying drawings, Figure 1 is a diagrammatic perspective view of the improved first-selector A as used in my system, having its line relays normally connected with the main exchange battery.

Fig. 2 is a similar view of an improved connector C used when one automatic subscriber calls another automatic subscriber.

Fig. 3 is a similar view of another improved connector B used by an automatic subscriber for establishing connection with manual subscribers.

Fig. 4 is a similar view of an improved selector E, usually known as the second-selector.

Figs. 5 and 6 taken together illustrate diagrammatically the main exchange office in the system, the automatic subscribers and switching apparatus being shown in Fig. 5, and the manual subscribers and switching apparatus being shown in Fig. 6. A clear idea will be had of the connection if Figs. 5 and 6 are arranged horizontally, the former to the left of the latter.

Fig. 7 shows still further apparatus of the central office automatic equipment. A clear understanding will be had of the arrangement if, after Figs. 5 and 6 are arranged as described, Fig. 7 is then placed beneath Fig. 5, so that the trunk conductors leading downwardly from the banks of the selector A (Fig. 5) are made to meet the conductors leading upwardly from the selector E (Fig. 7).

Figs. 5 and 6 show an automatic subscriber calling a manual subscriber, and Figs. 5 and 7 indicate the automatic subscriber calling another automatic subscriber, all of the said manual and automatic subscribers being connected with the main central exchange.

Fig. 8 illustrates diagrammatically a manual sub-central exchange the subscribers of which may be reached by the automatic subscribers or the manual subscribers of the main exchange by way of a trunking operator whose cord circuit is shown at D. It will be understood, of course, that the subscribers of the said sub-central (Fig. 8) may also communicate with each other through

their line operators by the use of any suitable cord circuit D'. As a means whereby the automatic subscribers may call the subscribers at the sub-central, shown in Fig. 6 8, the repeater F at the main exchange is provided.

Fig. 9 is a diagrammatic view showing a special form of cross-multiplying between automatic switch contacts and manual jacks.

10 It will be noticed that the circuits are so arranged that the manual operator of Fig. 6 may use the same trunk line to the cord circuit D (Fig. 8) to which the repeater F (Fig. 5) is connected; but the 15 circuits are so arranged that if an automatic subscriber seizes the trunk through the repeater F, or if the manual operator seizes the trunk, that particular trunk will be made busy to the exclusion of all operators or subscribers—that is, if the manual operator in Fig. 6 seizes the trunk line a guarding potential will be established through the medium of the repeater F to prevent any of the automatic subscribers 20 from using the said repeater F until the manual operator surrenders the use of the trunk; the reverse being the case if an automatic subscriber seizes the repeater F. In the following, Figs. 5 and 7 will be referred 25 to as the automatic department of the main exchange, Fig. 6 as the manual department of said exchange, and Fig. 8 as the sub-central office. It will be understood that the selectors A (Fig. 5) and A' (Fig. 7) are 30 identical, and that in the following it will be sufficient to describe the selector A. The second-selectors E of Figs. 5 and 7 are, of course, the same. It will also be understood that the cord circuit G is of a usual and well-known type of line operator's cord circuit, and that the operator's cord circuit D' may 35 be of any known or approved type. Furthermore, the automatic substations H and I are in turn of any suitable or approved 40 type. The same is true of the manual substations J, K, L and M. In the system various batteries are shown. In connection with the automatic department battery B' furnishes current for operating the automatic switches, which battery has its positive terminal preferably grounded at G'. In the manual department the batteries B² and b² are provided, with their positive terminals preferably grounded at G². At the 45 sub-central the battery B³ is shown having its positive terminal grounded at G³. Battery B', it is found, gives good results with a potential of from fifty to fifty-four volts; batteries B² and b² of twenty-four volts each; and battery B³ also of twenty-four volts.

The automatic substations, like the substation H, may be of any desired or approved type, and as shown comprises a receiver 2 and switch-hook 3, which latter has

radiating from its body a number of cam arms 4, 5 and 6, said hook being pivotally secured to the keyboard frame (not shown) by a screw 7 about which it swings when the receiver is removed. The swinging hook 70 is for the purpose of changing certain circuit connections to be disclosed. Furthermore, said substation has a transmitter 8, a ringer 9, an induction-coil 10 with a primary winding 11 and a secondary winding 12, a condenser 13, impulse-wheel 14 which has the usual vertical impulse teeth 15 that are adapted to operate the vertical impulse spring 16. In addition, the impulse wheel carries a rotary impulse tooth 17 which operates the rotary impulse spring 18. The cam arm 4 controls the so-called locking arm 19 in such a manner that when the switch-hook rises, and before the dial is rotated, the insulating tip 20 upon the end of the locking cam arm 19 that normally rests in the position shown at substation I is driven to the inner edge of the angled section of the ground spring 21, whereby when the dial is rotated by the calling subscriber the pin 22 upon the end of the locking dog 23 is able to pass beneath the locking cam to raise the said cam a trifle, causing the said insulating tip 20 to fall behind the said angled section of the ground spring 21, permitting the said spring, therefore, to make contact with a cooperating ground spring 24. The engagement of the ground springs 21 and 24 places the ground post 25 in connection with the substation ground G⁴, whereby when the subscriber releases the dial after rotating it, as described, the vertical impulse teeth 15 will cause the vertical impulse spring 16 to come in contact with the ground post 25; and immediately following, the rotary impulse tooth 17 causes the rotary impulse spring 18 to come in contact with the same ground post 25. When the switch-hook is down the cam arm 6 maintains the switch springs 26 and 27 in contact, thereby bridging the ringer 9 in series with the condenser 13 across the line. The springs 28 and 29 are then disengaged, and the primary winding 11, in series with the transmitter 8, is removed from across the line. Even after the switch-hook is raised, since the finger 30 of the cam dog 23 controls the engagement of the said springs 28 and 29, and since the said cam dog rotates in unison with the dial, if the dial is rotated the springs 28 and 29 and, therefore, the subscriber's line conductors are kept separated during said rotation. The signaling device whereby a subscriber may signal another after a connection has been established comprises a push-button 31 and spring 32, which latter normally engages the contact point 33; but when the push button 31 is pressed the spring 32 leaves the contact point 33 and engages the contact point 34 which is connected to the substation 130

ground G⁴. The means whereby the subscriber may release the central station apparatus brought into service comprises three springs 35, 36 and 37 commonly known as 5 release springs and so controlled by the cam arm 5 that when the switch-hook descends the released springs are brought into contact, thereby simultaneously grounding both sides of the subscribers' lines. The said cam arm 10 5 is provided with a lateral flange 38 that engages a corresponding lateral flange 39 upon the release spring 37 which, as the switch-hook descends, forces the said spring 37 to crowd the three release springs into 15 electric contact. When the switch-hook ascends, however, the flange 38 engages the flange 39 on the opposite side, so that the spring 37 is not pressed onto the spring 36 upon the upward motion of the switch-hook. 20 A somewhat similar provision is made for the vertical and rotary impulse springs 16 and 18. The former is provided with a flange 40 which is engaged by the vertical impulse teeth 15, and the latter, namely the 25 rotary impulse spring 18, is provided with a corresponding flange 41 which is engaged by the rotary impulse tooth 17.

The first-selector switch shown at A (Fig. 1) is an improved form of this type of selector. It embodies among other details the following: The switch-shaft 42 is a well-known and essential element of the switch and carries the vertical, rotary and private wipers 43, 44 and 45, respectively. Another 30 element of the switch, which is also well-known, is the side switch N. In the selector this side switch usually has four wipers only; but in the improved selector A it comprises five, namely the side switch wipers 46, 47, 48, 49 and 50. The wiper 46 performs a new 35 function which will be described. The said side switch, during the operation of the switch, passes through three successive positions commonly known as the first, second and third positions of the side switch. This 40 operation is controlled by the private magnet 51. The said wipers are, of course, rigidly connected together, and in the first position occupy, respectively, the contact points 52, 53, 54, 55 and 56; in second position they 45 occupy the contact points 57, 58, 59, 60 and 61; and in third position they occupy the contact points 62, 63, 64, 65 and 66. Through the medium of the vertical and rotary line 50 relays 67 and 68 the subscriber succeeds in operating the switch A before the side switch passes to third position, the operation of which switch is accomplished through the medium of the vertical and rotary magnets 69 and 70. The vertical and rotary line 55 relays 67 and 68 are used by the subscriber during the same period if he desires to energize the release magnet 71; but if the side switch passes to third position the control 60 of the switch is attained through the medium of the back release relay 72, which relay is included in the so-called trunk release circuit that comprises the private wiper 45. Among the improvements in the selector-switch A are the line switching bridge-cut-off relay 73 and the private normal relay 74. When a manual subscriber calls the subscriber H, for instance, the line switching bridge-cut-off relay 73 pulls up and connects the line conductors 75 and 76 leading 70 to the substation H with the jack normal conductors 77 and 78 that lead to the manual operator's position. Said relay also at the same time breaks the connection between the vertical and rotary line relays 67 and 68, 75 opening up the bridge across the line. When an automatic subscriber calls the automatic subscriber H the said relay 73 pulls up for the purpose of removing the bridge from 80 across the line. The private normal relay 74 is used, when a manual subscriber calls an automatic subscriber, for putting a guarding potential on the private normal conductor of the switch A, so that an automatic subscriber will not be able to establish 85 connection with the line. Said selector A, in addition to the mechanism thus far described, is provided with a shaft cam 79 for limiting the motion of the side switch when the side switch passes from first to second position. The longitudinal teeth 80 are employed by the rotary magnet 70 for rotating the shaft, and the circular teeth 81 are used by the vertical magnet 69 for giving the shaft 90 a vertical movement. The switch-shaft 42 is normally under the control of the coiled spring 82, which spring has one terminal fixed to the shaft and the other to the normal post arm 83. The switch-shaft carries, in addition, a normal post arm 84 for 95 controlling the off-normal springs 85 and 86 which are comprised in a supervisory circuit that passes through the supervisory lamp 87. If by accident the switch-shaft 42 is raised and retained raised, the lamp 87 100 continues to burn, so that the switch attendant can recognize the trouble at a glance and take steps toward restoring the switch to its normal condition, incidentally investigating the cause of the irregularity. The selector-switch is, of course, suitably provided with a line and private bank 88 and 89, respectively, with which the line and private wipers are respectively adapted to 105 engage.

The second-selector E (Figs. 4 and 7) is in general the same as the first-selector A, with the exception that it has no line switching bridge-cut-off relay such as the relay 73 at A (Fig. 5), nor a private normal relay 74; neither has it a side switch wiper similar to the side switch wiper 46. The second-selector has only four side switch wipers. The similar parts of the selectors A and E 110 are similarly represented. Said selector E 115

120

125

130

has, of course, its vertical and rotary line relays 90 and 91 and private magnet 92, vertical magnet 93, rotary magnet 94, release magnet 95, and back-release relay 179.

5 The connector C (Figs. 2 and 7) is of the general well-known type, but is adapted for common battery work, as here shown. It has the usual switch-shaft 97, switch-shaft wipers 98, 99 and 100, private and line banks 101 and 102, shaft cam 103, longitudinal teeth 104, circular teeth 105, coiled spring 106 for normally controlling the shaft, normal post arm 107 and switch-shaft springs 108 and 109. In addition there are the vertical and 15 rotary line relays 110 and 111, vertical magnet 112, rotary magnet 113, private magnet 114, release magnet 115 and the ringer relay 116, and also the back-bridge relays 117 and 118. For adapting the said switch to common 20 battery work there is provided a differential relay 119 having two windings 120 and 121 for controlling certain circuits to be pointed out. The said switch is, of course, provided with the usual side switch O and with the 25 double dog 122.

The connector-switch B (Figs. 3 and 5) is provided with the same details as the connector C (Fig. 7), with the exception that it has no private bank. It is of the common-battery type, and although the circuits are somewhat different the relays and mechanical details are, with the exception of the private bank, exactly the same in both switches. It will therefore only be necessary to refer 30 to each part of the connector B as they become involved in the circuits that follow. The main exchange is provided with a ringer generator 123 for furnishing ringing current to the automatic and manual departments of the main exchange. Since many of the features of the manual cord circuits that are used in this system are well known in the art, it will not be necessary to describe them in detail, since they will be 35 understood when reference is made to them during the description of the circuits to follow. A better understanding of the system may be had by following the operations of the subscribers in calling each other. It 40 will be noticed upon referring to the banks of the selector A (Fig. 5) that the different levels of the said banks are used for different connections. As indicated, the second level is used by the automatic subscribers for 45 establishing connections with the manual subscribers, the sixth level to call automatic subscribers of the main exchange, and the ninth level is used for establishing connections with the manual subscribers of the sub- 50 exchange. There are a number of levels from which no trunk conductors are shown leading. These levels may be used for any desired purpose—for example, for further 55 enabling connections between automatic and 60 automatic subscribers, or between automatic 65

and manual subscribers, as the business of the exchange may require. The arrangement of the bank levels, as shown, is not necessarily confined to the banks of the first-selectors. The bank levels of the second-selectors may be so used if it is advantageous in any way. Assuming that the subscriber at substation H (Fig. 5) wishes to call the subscriber at substation I (Fig. 7) whose substation number, it will be assumed, is 6220; he will proceed to operate his dial four times, first in accordance with the digit 6, then in accordance with the digit 2, then 2, and finally in accordance with the cipher or last digit. In each case the vertical line conductor 75 is grounded a number of times, corresponding to the numerical value of the particular digit to which the operation corresponds, and then the rotary line conductor 76 is grounded once, as is well known. The 70 operation of the dial, according to the digit 6, operates the selector A (Fig. 5) to the sixth level, from which level a trunk line is selected to some idle second-selector—for example, the second-selector E (Fig. 7), to 75 which the subscriber's lines are then extended. The second operation of the dial raises the wipers of the second-selector E to the second level, from which level an idle connector is selected to which the subscribers' lines are thenceforth extended—for example, the connector C. The connector C is then, as is well known, operated in accordance with the last two digits, so that connection is established with the desired substation 80 #6220, if the said substation is not busy. If it is busy the connector-shaft is released and a busy signaling circuit is set up between the said connector and the calling substation. In either case—that is, 85 whether a busy line is found or where the connection is fully established—the switching apparatus employed is restored to normal condition by the calling subscriber when the latter hangs up his receiver and grounds 90 both line conductors simultaneously. If the 95 automatic subscriber at substation H wishes to call a manual subscriber at substation M, the number of which station it will be assumed is 2220, the selector A is first operated 100 to the second level, and then the subscriber's line conductors are placed in connection with a second-selector E. The said selector is 105 in turn operated into connection with a connector B which, last of all, is carried into 110 connection with the desired line; or if the line is busy the usual busy signaling circuit is established upon the busy release of the connector-switch shaft. If the subscriber at 115 substation H wishes to call the subscriber K at the sub-central office (Fig. 8), he operates his dial to raise the wipers of his selector to the ninth level; the repeater F is then seized, 120 and a signal is transmitted to the trunking 125 operator at D (Fig. 8). The said operator 130

then comes in on the line and learns from the calling subscriber the number he desires, and then connects him directly to the line called for—in this case with the line leading 6 to the substation K. If the manual subscriber at station L of the main exchange (Fig. 6) wishes to call the automatic subscriber at substation H, he removes his receiver and signals the operator at G. She 10 comes in on the line by inserting her plug into jack *a*, at which time the calling subscriber informs her of the line desired. She then plugs the other end of the cord circuit G into the jack *b*, thus completing a connection 15 between the two subscribers as soon as the line switching relay 73 pulls up. If the subscriber at substation K (Fig. 8) wishes to call the subscriber H (Fig. 5), he signals his operator at D', who then signals the 20 trunking operator at D, informing her that the substation K wishes to connect with the substation H. The operator at D inserts the answering end of her cord circuit D into the jack *c* and, at the same time, signals the 25 manual operator at G over an order wire, which operator then answers by inserting the answering end of the cord circuit G into the jack *d'*. The said operator then inserts the calling end of said cord circuit G into 30 the jack *b*, establishing the desired connection. In any case where connection is established between automatic and manual subscribers, since the connection is made through cord circuits having front and back 35 supervisory signals, as soon as either or both subscribers leave the line the operator becomes aware of the fact and destroys the connection in the usual manner. In this system means are provided whereby calling 40 and called automatic subscribers have guarding potentials provided at their jacks *b*, so that the operator at G may make the usual busy test. Also, when an automatic subscriber calls through the repeater F the 45 trunk jacks *d'* are made busy to the operator at G, and vice versa—that is, if the operator at G calls the sub-central station by using the jack *d'* a guarding potential is provided at the selector banks A, so that an automatic 50 subscriber may not be able to come in on the line and interfere. This latter provision, of course, provides protection not only on connections between the main manual exchange (Fig. 6) and the sub-central (Fig. 8), but 55 also for connections from the said sub-central to the main manual department (Fig. 6).

The repeater F is a very simple switching device having any suitable base. It has no 60 such movable parts as switch-shafts and sliding contacts which characterize the step-by-step switches. It is provided with vertical and rotary line relays 124 and 125, a differential relay 126 with windings 127 and 65 128, an auxiliary relay 129, and a retarda-

tion-coil 130 and private trunk relay 131. The circuit that passes through said repeater is divided into two sections by the condensers 132 and 133. A feature to which special attention is called is the following: 70 Assuming that ten trunk lines are provided between the main exchange and the sub-central exchange, one will lead from each of the selector-bank contacts. To each of said trunks there is one jack similar to the jack *d'* (Fig. 6). There is also a repeater similar to the repeater F for each trunk line, the jack and the repeater being in multiple, as shown in Figs. 5, 6 and 8. Where the repeaters are all arranged to lead from the 75 contacts of the ninth level, for instance, of the selector line banks, the jacks and the selector bank contacts are arranged in reverse order, as indicated in Fig. 9. In said Fig. 9 the contacts of the ninth level of the line bank 88 of Fig. 1 are arranged from left to right in the order *e*¹, *e*², etc., and the jacks from left to right are arranged in the order *d*¹, *d*², etc. For example, the first bank terminal *e*¹ of the ninth level of the selector 80 line bank 88 (Figs. 1 and 9) is connected with the jack *d*¹⁰, and the jack *d*¹ is connected with the bank terminal *e*¹⁰. With such an arrangement, and if the manual operator always selects the trunk connections 85 from left to right, there will be a minimum loss of time from coming in contact with busy trunk lines. The same will be true with respect to the selector A and all other selectors whose bank contacts are in multiple 90 with the bank contacts of said selector A. 95

More in detail, the establishment of the connections between subscribers is as follows:

To call the automatic subscriber #6220 100 the subscriber at substation H operates his dial for the digits 6, 2, 2 and 0, as already explained.

The first digit being 6 the vertical line conductor 75 is grounded six times and then the 105 rotary line conductor 76 is grounded once. Grounding the said vertical line conductor energizes the vertical line relay 67 of the selector A six times, once each time that the impulse teeth 15 press the impulse spring 16 onto the ground post 25. The magnetizing current flows from the substation ground G⁴ through the ground springs 21 and 24 to the ground post 25, thence to the vertical 110 impulse spring 16, vertical line conductor 75, side switch wiper 49, contact point 55, conductor 134, line switching relay springs 135 and 136, conductor 137 to the vertical line relay 67, thence to the battery lead 138 and from battery B' to ground G⁵. The 115 vertical line relay upon pressing the line relay springs 139 and 140 into contact operates the vertical magnet 69 by sending a flow of current from the substation ground G⁵ through the springs 139 and 140, con- 120 125 130

ductor 141, private springs 142 and 143 to the vertical magnet 69, thence through the battery lead 138 and from battery B' to ground G'. The vertical magnet 69 then 5 operates to raise the shaft 42 six steps, carrying the line and private wipers 43, 44, and 45 opposite the first contact of the sixth level of the line and private banks 88 and 89. The ground impulse to the rotary line conductor 76 that follows immediately after 10 energizes the first-selector rotary line relay 68. The current passes from substation ground G^a to the rotary impulse spring 18, thence through the rotary line conductor 76, side switch wiper 50, contact point 56, conductor 144, line switching relay springs 145 and 146, rotary line relay 68 to the battery lead 138, thence through battery B' to ground G'. The rotary line relay upon 15 closing connection between the line springs 147 and 139 energizes the private magnet 51, which magnet then operates to release the side switch N from first to second position. The magnetizing current for the private magnet flows from ground G^a through the springs 139 and 147, conductor 148, private magnet 51 to the battery lead 138 and through battery B' to ground G'. As soon 20 as the side switch passes to second position the side switch wiper 47 passes onto the grounded contact point 58, whereby the energizing circuit for the rotary magnet 70 is completed from ground G^a through the said side switch wiper 47, conductor 149, 25 through one coil of the rotary magnet 70, interrupter springs 150, through the second coil of said rotary magnet 70, to the battery lead 138, thence through battery B' to ground G'. 30 The rotary magnet then operates to rotate the shaft one step, carrying the wipers into engagement with the first contact. If the private wiper 45 finds the first contact grounded—that is, if the first trunk line is 35 busy, the private magnet 51 again energizes before the side switch has time to leave the second position, locking the side switch in said second position until the private wiper is carried beyond the last busy contact by 40 the interrupted operations of the rotary magnet 70. The energizing circuit for the private magnet 51 in this instance extends from the grounded private bank contact to the private wiper 45, thence through the conductor 151, back release relay 72, conductor 152, side switch wiper 48, contact point 59, conductor 153 to the private magnet 51, thence to the battery lead 138 and from battery B' to ground G'. Assuming 45 that all the trunk lines are busy except the last one on the sixth level, the rotary magnet 70 continues to rotate the shaft until the line wipers are carried onto the trunk conductors 154 and 155 that lead to the second selector E (Fig. 7). At the same time the

private wiper 45 is carried into engagement with the trunk release conductor 156. When the private magnet 51 and the rotary magnet 70 de-energize at the same time the side switch is then permitted to pass to third 70 position, whereby the subscriber's line conductors 75 and 76, by way of the conductors 157 and 158, are placed in connection with the trunk conductors 154 and 155, respectively. At the same time a guarding potential is established at the private wiper 45 when the side switch wiper 48 engages the grounded contact point 64. Said guarding potential is then applied to the tenth 75 private contact of the sixth level of the private bank 89 for protecting the seized trunk line from interference. The circuit over which the said guarding potential is established extends from ground G^a at the side switch N of the selector A to the side switch 80 wiper 48, thence through the back-release relay 72 and conductor 151 to the private wiper 45, and to the engaged contact. The guarding potential is established, from the same ground G^a, at the connector private 85 bank contacts by way of the private normal conductor 159, so that no calling subscriber may call in upon the calling line until after the switches are restored. It will be noticed that the jack sleeve 160 of the jack b (Figs. 95 1 and 6) is normally connected, through the private normal relay 74 and the side switch wiper 46, with the grounded contact point 52, whereby when the operator plugs in at the jack b the private normal relay 74 is 90 energized from main battery B^a (Fig. 6) to the ground terminal G^a. The said private normal relay 74 then causes the energizing of the line switching relay 73 from ground G^a by way of the side switch wiper 48 to 100 battery B', for purposes heretofore explained. But when the side switch wiper 46 passes to third position the potential or polarity of the jack sleeve 160 is changed 105 from positive to negative, whereby the operator may receive the busy test indicating that the line of the substation H is busy. This guarding potential is set up over the following circuit: from the said jack sleeve 160 through the private normal relay 74 to the side switch wiper 46, thence to the contact point 62 and through the line switching relay 73 to the negative or non-grounded 110 terminal of battery B'. After the selector A has thus been operated by the first operation of the dial the second operation is 115 directed to the second-selector E. The relays 74 and 73 do not, of course, energize when the operator tests for busy, since the said relays are, respectively, five hundred and thirteen hundred ohms, more or less. 120

The second digit being 2 the subscriber grounds the vertical line conductor 75 twice and the rotary line conductor 76 once. The impulses to the vertical line conductor 75 125

energize the vertical line relay 90 of the second-selector E. In the energizing circuit the current passes from the substation ground G^4 to the vertical line conductor 75, 5 thence through the side switch wiper 49 of the first-selector A (Figs. 1 and 5) to the contact point 65, thence over the conductor 157, vertical line wiper 43 to the vertical trunk conductor 154, thence to the side 10 switch wiper 161 of the second-selector E (Figs. 4 and 7) to the contact point 162, thence through the vertical line relay 90 to the battery lead 138 and through battery B' to ground G'. The vertical line relay 90 15 upon pressing the springs 163 and 164 together sends energizing current through the vertical magnet 93 from ground G^9 through the said springs 163 and 164 and through the private springs 165 and 166 to the vertical 20 magnet 93, thence to the battery lead 138 and from battery B' to ground G'. The vertical magnet 93 operates to raise the switch-shaft 167 two steps, carrying the line and private wipers 168, 169 and 170 opposite the first contact of the second level 25 of the line and private banks 171 and 172, respectively. After the vertical line conductor 75 is thus grounded to operate the switch-shaft 167 of the second-selector E 30 vertically, the grounding of the rotary line conductor 76 brings about the rotation of said shaft by energizing the rotary line relay 91 at the selector E. The energizing current passes from ground G^4 at the substation (Fig. 5) to the rotary line conductor 35 76, thence to the side switch wiper 50 of the first-selector A, through said side switch wiper to the contact point 66, thence over the conductor 158 to the rotary line wiper 44 and to the rotary trunk conductor 155. The current then continues to the side switch wiper 173 of the second-selector E, and 40 through said wiper to the contact point 174, thence through the rotary line relay 91 to the battery lead 138 and through battery B' to ground G'. The rotary line relay then 45 operates to close connection between the line relay springs 175 and 163 for energizing the private magnet 92. The circuit for 50 conducting the magnetizing current extends from ground G^9 through the said springs 163 and 175 to the private magnet 92, thence to the battery lead 138 and through battery B' to ground G'. The operation of the private magnet permits the side switch of the 55 second-selector E to pass to second position, as described in connection with the first-selector A, whereby the side switch wiper 176 passes into engagement with the grounded contact point 177, closing the energizing 60 circuit for operating the rotary magnet 94. The said circuit is established from ground G^{10} through the contact point 177 and side switch wiper 176 to the rotary magnet 94 and through the interrupter spring 178 to 65 the battery lead 138 and through battery B' to ground G'. The rotary magnet then operates to rotate the switch-shaft until the wipers are carried beyond all busy trunk lines, during which time the private magnet 70 92, as already explained, locks the side switch in second position. As in the first-selector the energizing circuit for the private magnet 92, while the side switch is in second position, extends from the grounded 75 private bank contact to the private wiper 170, thence through the back-release relay 179 and side switch wiper 180 to the contact point 181', thence through the private magnet 92 to the battery lead 138 and through 80 battery B' to ground G'. Assuming that the wipers are carried to the tenth contact of the second level the line wipers 168 and 169 are, therefore, respectively connected with the vertical and rotary trunk conductors 181 and 182 that lead to the connector C. At the same time the private wiper 170 is placed in engagement with the trunk-release conductor 183 that also leads to said connector C. The subscriber's line conductors being thus extended to the connector C the next operation of the subscriber's dial is directed to said switch. 85

The third digit being 2 also, the vertical and rotary line conductors 75 and 76 are grounded, the former twice and the latter once. The impulses to the former operate the line relay 110 of the connector C, together with the differential relay 119 of said connector (Figs. 2 and 7), since the said vertical line relay and one of the windings of the differential relay are connected in series. This energization of said differential relay does not play any part in the switch operations. The energizing circuit, however, extends from the substation ground G^4 90 (Fig. 5) to the vertical line conductor 75, thence through the side switch wiper 49 of the first-selector A to the vertical trunk conductor 154 and to the side switch wiper 161 95 of the second-selector E, thence to the contact point 184, conductor 185 and vertical line wiper 168 to the vertical trunk conductor 181 and to the vertical line relay 110 100 of the connector C, thence through said relay and through the winding 121 of the differential relay 119 to the battery lead 138, and through battery B' to ground G'. The said vertical line relay upon acting establishes a circuit through the vertical magnet 112 from the ground G^{11} 105 when the springs 186 and 187 are carried into contact. The current flows from the said ground G^{11} through the said springs 186 and 187, and through the private springs 188 and 189 to the conductor 190, thence to the side switch wiper 191 and contact point 192 to the vertical magnet 112, thence to the battery lead 138 and through battery B' to ground G'. The vertical magnet 112 operates to raise 110 115 120 125 130

the switch-shaft 97 two steps, carrying the line wipers 98 and 99 and the private wiper 100 opposite the first contact of the second level of the line and private banks 102 and 101, respectively. The ground impulse to the rotary line conductor 76, following the impulses to the vertical line conductor 75, is received by the rotary line relay 111 of the connector C and by the differential relay 119, both of which relays operate, but the latter to no effect. The circuit begins with the substation ground G⁴ and extends over the rotary line conductor 76 to the side switch wiper 50 of the selector A, thence to the rotary trunk conductor 155 and to the side switch wiper 173 of the second-selector E, contact point 193, conductor 194, rotary line wiper 169 to the rotary trunk conductor 182, thence through the rotary line relay 111 and winding 120 of the differential relay 119, conductors 195 and 196, springs 197 and 198 of the rotary back-bridge or pole-changing relay 118 to the battery lead 138 and through battery B' to ground G'. The rotary line relay 111, therefore, operates to press the spring 199 onto the ground spring 186 for energizing the private magnet 114. The current through said private magnet extends from ground G¹¹ through the said springs 186 and 199 to the private magnet 114, conductors 200 and 201 to the pole-changing relay springs 197 and 198 to the battery lead 138 and through battery B' to ground G'. The private magnet 114 upon operating permits the side switch O to shift to second position. The movement of the side switch carries the side switch wiper 191 onto the side switch contact point 202, thereby substituting the rotary magnet 113 in place of the vertical magnet 112 to the control of the vertical line relay 110. The fourth digit being 0 the subscriber operates to ground the vertical line conductor 75 ten times and the rotary line conductor 76 once. Since the side switch wiper 191 is shifted as described, the ground impulses to the vertical line conductor 75—which, of course, operate the vertical line relay 110, as already explained—cause the step-by-step operation of the rotary magnet 113. The said rotary magnet is energized each time that the vertical line relay 110 presses the line relay springs 186 and 187 into contact. The current-flow may be traced from ground G¹¹ through the said springs to the side switch wiper 191, thence through the contact point 202 of the side switch to the rotary magnet 113, thence through battery lead 138 and through battery B' to ground G'. The rotary magnet being operated ten times, the line wipers 98 and 99 are carried into engagement with the normal conductors 203 and 204, respectively, and the private wiper 100 into engagement with the private normal conductor 205. The

ground impulse to the rotary line conductor 76, after the connector wipers are carried into engagement with the desired line, causes either of two operations—the final establishment of a connection, or the busy release of the connector-switch shaft if the called line is busy. For the present it will be assumed that the connection is established and that the side switch O of the connector passes to third position. This, of course, occurs when the rotary line relay 111 operates and in turn energizes the private magnet 114, as already explained. The shifting of the side switch to third position accomplishes the following results: First, the subscriber's extended line conductors 181 and 182 between the second-selector E and the connector C are placed in connection with the normal conductors 203 and 204. The former (namely the conductor 181) is placed in connection with the normal conductor 203 through the condenser 206, ringer relay springs 207 and 208, side switch wiper 209, contact point 210, conductor 211, vertical line wiper 98 to the vertical line conductor 203. The conductor 182 is placed in connection with the rotary normal conductor 204 through the condenser 212, ringer relay springs 213 and 214, side switch wiper 215, contact point 216, conductor 217 and rotary line wiper 99.

To signal, the connection being established, the calling subscriber presses his signaling button 31, thereby grounding the vertical line conductor 75 and energizing as a result the vertical line relay 110 of the connector C. The energizing circuit extends from the substation ground G⁴ through the ground springs 21 and 24 to the contact point 34, thence through the signaling button spring 32 and primary circuit springs 29 and 28 to the vertical line conductor 75, thence through the vertical line relay 110 at the connector C and winding 121 of the differential relay 119 to the battery lead 138, thence through battery B' to ground G'. As previously stated, when the vertical line conductor 75 is grounded alone both the vertical line relay 110 and differential relay 119 energize. Therefore, when the subscriber presses his signaling button the vertical line relay 110 energizes, pressing the line relay springs 186 and 187 into contact; and the differential relay 119 energizes, separating the spring 218 from the spring 219 and carrying it into engagement with the spring 220. The combined operations of said line and differential relays establish an energizing circuit through the ringer relay 116 from the connector ground G¹¹, through the line relay springs 186 and 187, private magnet springs 188 and 189 to the side switch wiper 191, thence to the contact point 221 and to the ringer relay 116, thence through the differential relay springs 220 and 218 to

the battery lead 138 and through battery B' to ground G'. The ringer relay operates to disconnect the calling subscriber's line from the called subscriber's line by separating the respective springs 208 and 214 from the springs 207 and 213 and carrying the former into engagement with the springs 222 and 223. The said springs 222 and 223 constitute the terminals of the ringer generator 123 (Fig. 5), while the springs 208 and 214 constitute the terminals of the called subscriber's line. A ringing current is sent over the called line from the ringer generator 123 to the conductor 223', the ringer relay springs 222 and 208 to the side switch wiper 209, contact point 210, vertical line wiper 98, vertical normal conductor 203, vertical line conductor 224, condenser 225, ringer 226, springs 227 and 228, rotary line conductor 229, rotary normal conductor 204, rotary line wiper 99, side switch contact point 216, side switch wiper 215, ringer relay springs 214 and 223 to the conductor 214' and back to the ringer generator 123.

25 The called subscriber upon answering bridges his transmitter 230 and primary winding 231 across the line and establishes a circuit comprising the back-bridge relays 118 and 117 of the connector C and the transmitter 230 of the substation I in series. This circuit is made possible from the fact that the side switch wiper 232 is now in third position and in engagement with the contact point 233 and the ground G¹³. The energizing current that is thus supplied is utilized for talking purposes at the substation, and for switching purposes at the connector C, through the medium of the pole-changing relay 118. The current flows from ground G¹³ to the contact point 233, thence to the side switch wiper 232, pole-changing relay 118, ringer relay springs 213 and 214, side switch wiper 215, contact point 216, rotary line wiper 99, rotary normal conductor 204, rotary line conductor 229, and through the primary winding 231 and transmitter 230 to the vertical line conductor 224, thence to the vertical normal conductor 203, vertical line wiper 98, contact point 210, side switch wiper 209, ringer relay springs 208 and 207, vertical back-bridge coil 117, and through the differential relay springs 219 and 218 to the battery lead 138, thence through battery B' to ground G'. The called subscriber is thus furnished with talking battery current for his transmitter, which current, as already stated, at the same time operates the pole-changing relay 118. The said pole-changing relay thus shifts the spring 197 away from the spring 198 onto the ground spring 235. The shifting of said spring 197 closes the circuit through the transmitter 8 of the substation H (Fig. 5) as follows: from ground G¹³ at the connector side switch O to the contact point 233, jack f. It will be seen, therefore, that when

30 side switch wiper 232, pole-changing relay springs 235 and 197 to the rotary line relay 111, thence through said relay to the rotary trunk conductor 182, rotary line wiper 169 of the second-selector E, side switch contact 70 point 193, side switch wiper 173, rotary trunk conductor 155 to the rotary line wiper 44 of the selector A, side switch contact point 66, side switch wiper 50, rotary line conductor 76, primary winding 11 at the 75 substation H, transmitter 8, vertical line conductor 75, side switch wiper 49 of the first-selector A, contact point 65, vertical line wiper 43, vertical trunk conductor 154, side switch wiper 161 of the second-selector 80 E, contact point 184, vertical line wiper 168, vertical trunk conductor 181, vertical line relay 110 of the connector C, winding 121 of the differential relay 119 to the battery lead 138 and through battery B' to ground 85 G'. The two subscribers, being thus provided with talking battery current, will converse over the circuits through which the said talking current is flowing, which circuits are, of course, connected by the condenser 206 on one side of the battery and the condenser 212 on the other side of the battery, as clearly shown in Fig. 7. While the subscribers are thus connected they are protected from interference by any other automatic subscriber who may try to establish connection with the already called subscriber by a guarding potential that appears at the private wiper 100, and at the engaged 90 private contact, when the side switch wiper 232 engages the grounded contact point 233. This guarding potential is established from the connector side switch ground G¹³ through the side switch wiper 232 to the private wiper 100, and thence to the engaged 95 contact; but not only does this guarding potential protect against interference by automatic subscribers, but also from interference by the manual subscribers, through the medium of the following arrangement: 100 The establishment of the guarding potential at the private wiper 100 of the connector C furnishes current for energizing the bridge-cut-off line switching relay 236 of the first-selector A' from the private wiper 100 to the 105 private normal conductor 205, conductor 237, side switch wiper 239, contact point 240, conductor 241 to the line switching relay 236, thence to the battery lead 138 and through battery B' to ground G'. When the 110 line switching relay 236 pulls up, the springs 242 and 243 are then pressed together, so that the sleeve 244 of the jack f (Figs. 7 and 6) allotted to the line of the substation #6220 is connected to the negative terminal 115 of the battery B'. When the case the operator at the manual 120 department will get a busy test by applying her plug-tip to the sleeve 244 of the 125 jack f. It will be seen, therefore, that when

In that case the operator at the manual department will get a busy test by applying her plug-tip to the sleeve 244 of the jack f. It will be seen, therefore, that when

an automatic subscriber calls another automatic subscriber, as explained in the foregoing, the calling subscriber makes his line busy when the side switch wiper 48 of his selector A passes to third position; and the side switch wiper 48 in passing to third position connects the private normal conductor 159 with the side switch ground G⁷, establishing connection between the side switch ground G⁷ and the connector private bank contacts that correspond to the substation H. The called line is protected by a guarding potential established at the private wiper 100 of the connector C (Figs. 2 and 7) when the connector side switch wiper 232 engages the side switch ground contact 233 that connects with the ground G¹³; and the said called line is protected against calls from the manual subscribers by a guarding potential established at the sleeve 244 of the jack f allotted to the substation #6220 (Figs. 6 and 7) when the line switching relay 236 of the called selector A' (Fig. 7) presses the line switching relay springs 243 and 242 into contact. It will be understood, of course, that the calling subscriber has such control over the switching apparatus that he may release said apparatus either while the called subscriber's receiver is on the hook or while it is off the hook. It will be well to consider first the circuits that are involved in the release if the calling subscriber hangs up his receiver while the called subscriber's receiver is on the said called subscriber's switch-hook.

The release while the called subscriber's receiver is on the switch-hook occurs when the calling subscriber restores the receiver 2 to the switch-hook 3 as the said switch-hook descends. The release springs 35, 36 and 37 at the substation H are pressed into contact and the vertical and rotary line conductors 75 and 76 are grounded simultaneously. The vertical and rotary line conductors 75 and 76 are therefore grounded simultaneously from the substation ground G⁴ to the ground release spring 37, thence through the springs 36 and 35 to the vertical and rotary line conductors 75 and 76. The vertical and rotary line relays 110 and 111 of the connector C energize simultaneously, pressing the trunk release springs 245 and 246 into engagement, while at the same time the differential relay 119 energizes, since the current is flowing through both of the windings 120 and 121 in parallel, maintaining the said differential relay energized. The engagement of the trunk release springs 245 and 246 sets up an energizing circuit for magnetizing the connector release magnet 115 in series with the second-selector back-release relay 179. The connector release magnet 115 upon energizing attracts the release armature 247, which armature oper-

ates to restore the double dog 122 to normal position. The energizing circuit for the said release magnet 115 and the back-release relay 179 extends from ground G²¹ at the side switch of the second-selector E 70 to the side switch wiper 180, thence to the back-release relay 179 to the private wiper 170, and to the trunk release conductor 183, thence to the trunk release springs 245 and 246 of the connector C to the release magnet 115 and through the differential relay springs 220 and 218 to the battery lead 138, thence through battery B' to ground G'. As a result the switch-shaft 97 falls to normal position by well known means, and the side switch is driven to first or normal position by the double dog arm 248 acting upon the side switch link 249. Of course, the line relays 111 and 110 of the connector remain energized as long as the substation release springs 35, 36 and 37 remain together, and consequently the release magnet 115 of the connector C and back-release relay 179 of the second-selector E will remain magnetized during the same interval. The energization of the back-release relay 179 of the second-selector E causes the closure of contact between the back-release relay springs 250 and 251, whereby an energizing circuit is established through the release magnet 95 of the second-selector E and the back-release relay 72 of the first-selector A in series. The energizing circuit through said release magnet and back-release relay (Figs. 1 and 4 or 5 and 7) extends from the side switch ground G⁷ at the first-selector A to the contact point 64, side switch wiper 48, back-release relay 72, conductor 151, private wiper 45, trunk-release conductor 156 to the springs 251 and 250 of the second-selector E, thence through the release magnet 95 to the battery lead 138 and through battery B' to ground G'. The release magnet upon magnetizing attracts its armature 251, thrusting the release link 252 over the lug 253 of the double dog 254, placing the mechanism in readiness to restore the switch as soon as the energizing circuit opens and the substation release springs 35, 36 and 37 disengage. The back-release relay 72 of the first-selector A upon energizing presses the springs 255 and 256 into contact, closing in turn the energizing circuit of the release magnet 71 of the first-selector A from ground G¹⁴ through the said springs 255 and 256 and through the release magnet 71 to the battery lead 138, thence through battery B' to ground G'. The said release magnet 71 also attracts its armature 257, which latter then causes the release link 258 to engage the lug 259 of the double dog 260, placing the mechanism in readiness to restore the selector-switch. As soon as the subscriber's switch-hook descends sufficiently to permit the substation release springs 35, 36 and 37

37 to separate, the energizing circuits through the line relays 110 and 111 of the connector C are then destroyed, so that the said relays permit the trunk-release springs 245 and 246 to separate. The separation of said release springs 245 and 246 destroys the energizing circuit through the connector release magnet 115 and back-release relay 179 of the connector C and selector E. The connector C is thus fully restored and the selector E is also fully restored as soon as the back-release relay 179, upon de-energization, permits the springs 250 and 251 to break the magnetizing circuit for the release magnet 95, whereby the switch-shaft and side switch of said selector are restored to normal position in a well-known manner. Since the back-release relay 72 of the first-selector A is included in a series circuit with the release magnet 95 of the selector E, the said back-release relay also de-energizes, permitting the springs 255 and 256 to separate, in turn causing the de-energization of the release-magnet 71 of the selector A, which latter produces a full restoration of the switch. It will be evident, therefore, that by thus hanging up his receiver the calling subscriber restores all of the switching apparatus that he temporarily monopolized, restoring said switches at the same time to normal condition. If the automatic subscriber at substation H desires to call the manual subscriber #2220 (Fig. 6) he operates his dial in the same manner as if he were calling the subscriber #6220, with the exception that now the operations correspond to the digits 2, 2, 2, and 0.

The release after the called subscriber answers—that is, while the receiver of the called subscriber is off the switch-hook—occurs in a manner different from the release while the said receiver is on the switch-hook. In the former case the calling subscriber proceeds as usual by hanging up his receiver, and the switch-hook upon descending presses the release springs 35, 36 and 37 into contact, grounding the vertical and rotary line conductors 75 and 76 simultaneously. Attention has been called to the fact that the called subscriber upon removing his receiver energizes the pole-changing relay 118 of the connector C (Fig. 7), which pole-changing relay then operates to shift the rotary side of the line to ground by carrying the pole-changing relay spring 197 into engagement with the spring 235 while the connector side switch is in third position. Evidently, therefore, the inside terminal of the line that passes through the rotary line relay 111 of the connector C, and through the winding 120 of the differential relay, is grounded at the connector side switch ground G¹³. Consequently, the result of grounding the subscriber's rotary line conductor 76 at the substation H short-circuits the said line relay 111 and the winding 120 of the differential relay 119 through ground. The effect of thus short-circuiting the said relay coils is to cut short the flow of current through them. The primary effect of the cessation of the flow of current through this section of the circuit is to cause the differential relay 119 of the connector C (Figs. 2 and 7) to energize, since the flow of energizing current through the winding 121 of said differential relay is still maintained. In this instance the current flows from the substation ground G⁴ to the ground release spring 37, thence to the release spring 36 and to the vertical line conductor 75, and by paths already described through the vertical line relay 110 and through the said differential winding 121 to the battery lead 138, thence through battery B' to ground G'. The differential relay upon energizing causes a separation of the springs 218 and 219 and the engagement of the spring 218 with the spring 220. The separation of said springs 218 and 219 destroys the circuit that provides the called subscriber's transmitter with talking battery current through the vertical and rotary back-bridge coils 117 and 118. Evidently, then, the rotary back-bridge relay 118 will de-energize with the result that the spring 197 leaves the ground spring 235 and returns into normal engagement with the spring 198 that connects with the non-grounded terminal of the battery B', thus restoring the connection between the release magnet 115 and the non-grounded terminal of battery B'. The energizing of the differential relay 119 follows the de-energization of the rotary line relay 111, and the consequent separation of the trunk-release springs 245 and 246; but the de-energization of the pole-changing or rotary back-bridge relay 118 that immediately follows, as described, removes the short-circuit through the rotary line relay 111 and winding 120 of the differential relay 119, and reverses the connection so that a flow of current is now established through said winding 120 and rotary line relay, causing the rotary line relay to pull up again and establish connection between the trunk-release springs 245 and 246, the current in the winding 120 further strengthening the differential relay 119 which is already energized. Eventually, then, the trunk release circuit is again established that comprises the release magnet 115 of the connector C and the back-release relay 179 of the second-selector E. The result is that the connector-switch shaft 97 and side switch O are restored, as already explained, whereby the connecting circuit with the called line is destroyed as soon as the line wipers leave

- their engaging terminal; and, furthermore, the bridge-cut-off and line switch relay 236 of the first-selector A' is also de-energized as soon as the private wiper 100 leaves the 5 private normal conductor 205. The remaining part of the releasing operation is identically the same as that described when the calling subscriber releases while the called subscriber's receiver is on its switch-hook.
- 10 To call the manual subscriber #2220, therefore, the subscriber at substation H operates his dial in accordance with the digit 2, with the result that the vertical and rotary line conductors 75 and 76 are ground- 15 ed, the former twice and the latter once, whereby the vertical and rotary line relays 67 and 68 of the selector A are operated to raise the shaft 42 of the selector A two steps, carrying the line wipers 43 and 44 20 and the private wiper 45 opposite the first contact of the second level of their respective banks 88 and 89. Then the switch-shaft is rotated automatically, carrying the wipers into engagement with some idle 25 trunk line leading to a selector E. Although the second-selector E shown in Fig. 5 is represented leading from the second level, and the selector E shown in Fig. 7 is represented leading from the sixth level, still 30 for convenience of illustration it will be assumed that both selectors are identical. Therefore, the trunk conductors of both views will be given the same reference characters. In actual practice it is customary 35 to give each terminal in each level a special switch. Assuming that the first-selector A automatically rotates the line wipers 43 and 44 onto the tenth contact of the second level of the line bank 88, and that it establishes 40 connection with the trunk conductors 154 and 155 when the switch comes to a standstill, the subscriber's line conductors 75 and 76 will then be extended to the second-selector E, after receiving the impulses 45 responding to the second digit of the number 2220.
- The second digit being 2 the vertical and rotary line conductors 75 and 76 are grounded, twice and once respectively, and the vertical and rotary line relays 90 and 91 of 50 the second-selector E operate to raise the second-selector line and private wipers 168, 169 and 170 to the second level, after which operation they are then automatically rotated onto an idle trunk line leading to some connector. It is assumed that the trunk line thus seized leads to the connector B, the selector E automatically rotating the shaft 167 55 until the line wipers 168 and 169 are carried into engagement with the trunk conductors 181 and 182, and the private wiper 170 into engagement with the private normal conductor 183. The subscriber's line conductors are, therefore, extended to the 60 connector B which now receives the impulses

corresponding to the third and fourth digits of the desired number (Figs. 3 and 5).

The third digit being 2 the vertical and rotary line conductors 75 and 76 are grounded, twice and once respectively, whereby the vertical and rotary line relays 261 and 262 of the connector B are operated. The energizing circuit for operating the vertical line relay 261 extends from the substation ground G⁴ to the vertical line conductor 75 75 75, thence through the side switch wiper 49 of the first-selector A to the contact point 65, vertical line wiper 43, vertical trunk conductor 154, side switch wiper 161 of the second-selector E, contact point 184, vertical line wiper 168, vertical trunk conductor 181 80 to the vertical line relay 261, thence through the winding 162 of the differential relay 163 to the battery lead 138, and through battery B' to ground G'. The differential relay 163, 85 during the impulse for the third digit, energizes in series with the vertical and rotary line relays 261 and 262, but with no result of consequence. The vertical line relay 261 upon pressing the line relay springs 264 and 265 90 into contact causes the operation of the vertical magnet 266 over the following circuit: From ground G¹⁵ through the springs 265 and 264, private springs 267 and 268 to the vertical magnet 266, side switch contact point 269, side switch wiper 270 to the battery lead 138, and through battery B' to ground G'. The vertical magnet, therefore, operates to raise the shaft 271 two 95 steps, carrying the line wipers 272 and 273 100 opposite the first contact of the second level of the line bank 274. The ground impulses to the rotary line conductor 76 operate the rotary line relay 262 of the connector B over a circuit extending from ground G⁴ at the 105 substation H to the rotary line conductor 76, thence to the side switch wiper 50, contact point 66, rotary line wiper 44, rotary trunk conductor 155, side switch wiper 173 of the second-selector E, contact point 193, 110 rotary line wiper 169, rotary trunk conductor 182 to the rotary line relay 262, thence through the winding 275 of the differential relay 163 and through the ringer relay springs 276 and 277 to the battery 115 lead 138, thence through battery B' to ground G'. The rotary line relay 262 upon energizing carries the spring 278 onto the ground spring 265, energizing the private magnet 279 by a flow of current from ground G¹⁵ through the springs 265 and 278 to the 120 private magnet 279, thence through the ringer relay springs 276 and 277 to the battery lead 138, and through battery B' to ground G'. The operation of the private magnet 279 causes the side switch P of the connector to pass from first to second position. The passage of the side switch from first to second position carries the side switch wiper 270 onto the contact point 280, substi- 125 130

tuting the rotary magnet 281 under the control of the vertical line relay 261 in place of the vertical magnet 266.

The fourth digit being 0 the subscriber 5 operates his dial correspondingly and grounds his vertical line conductor 75 ten times and the rotary line conductor 76 once. Grounding the vertical line conductor 75 causes the energization of the connector vertical line relay 261 (Figs. 3 and 5), as above, and each time that the said relay 10 presses the said springs 264 and 265 into engagement the rotary magnet 281 instead of the vertical magnet 266 becomes energized through the following circuit: from ground G^{15} through the line relay springs 265 and 264, through the private springs 267 and 268 to the rotary magnet 281, thence to the contact point 280 and side switch 20 wiper 270 to the battery lead 138, thence through battery B' to ground G' . The rotary magnet then rotates the shaft 271 step-by-step, bringing the line wipers 272 and 273 into engagement with the tenth terminal of 25 the second level of the line bank 274, and into engagement with the normal conductors 282 and 283 allotted to the manual substation #2220. The ground impulse to the rotary line conductor 76 of the substation H causes the energization of the rotary line 30 relay 262, as before; therefore, the private magnet 279 is again energized, and if the desired line is not busy the side switch P passes to third position, finally connecting 35 the calling line with the called line; but if the desired line is busy, as will be explained, the connector-switch will be released upon the energization of the private magnet 279. Considering first that the side switch passes 40 to third position and that the connection is established, it will be evident that as soon as the side switch wiper 284 passes into engagement with the contact point 285 the energizing circuit for the ringer relay 286 is established from ground G^{16} to the contact 45 point 285, through the side switch wiper 284 and ringer relay 286 to the conductor 287, thence through the differential relay springs 288 and 289, conductor 290 and contact point 291 of the side switch to the side 50 switch wiper 270, thence to the battery lead 138 and through battery B' to ground G' . The ringer relay 286 then pulls up and carries the springs 292 and 293 into engagement 55 with the ringer relay springs 294 and 295, respectively, whereby the subscriber's extended line conductors 181 and 182 are placed in connection with the normal conductors 282 and 283, when the side switch 60 wipers 296 and 297 engage the contact points 298 and 299, respectively. The former, namely the conductor 181, establishes connection through the condenser 300, conductor 301, ringer relay springs 294 and 292, side 65 switch wiper 296, contact point 298, con-

ductor 302, vertical line wiper 272 to the vertical normal conductor 282. The conductor 182 establishes connection through the condenser 303, conductor 304, ringer relay springs 295 and 293, through the side 70 switch wiper 297, contact point 299, conductor 305, rotary line wiper 273 to the rotary trunk conductor 283. In the connector B (Figs. 3 and 5) the ringer relay 286 acts as a pole-changing relay, and as soon 75 as the springs 276 and 306 come into contact, when the said relay energizes, the calling subscriber's transmitter is provided with talking current from ground G^{17} through the ringer relay springs 306 and 276, and 80 through the winding 275 of the differential relay 163 and rotary line relay 262 to the rotary trunk conductor 182, thence to the rotary line wiper 169 of the second-selector E side switch contact point 193, side switch 85 wiper 173, rotary trunk conductor 155, rotary line wiper 44 of the first-selector A, side switch contact point 66, side switch wiper 50, rotary line conductor 76, primary winding 11 and transmitter 8 at the substation 90 H (Fig. 5) to the vertical line conductor 75, thence to the side switch wiper 49 of the first-selector A, contact point 65, vertical line wiper 43, vertical trunk conductor 154, side switch wiper 161 of the second-selector 95 E, contact point 184, vertical line wiper 168, vertical trunk conductor 181 to the vertical line relay 261 of the connector B, thence through the winding 162 of the differential relay 163 to the battery lead 138, and 100 through battery B' to ground G' . The talking current through the differential relay 163 does not energize the said relay, because the windings are connected in series 105 at the time; but the vertical and rotary line relays 261 and 262 energize, bringing the trunk-release springs 245^a and 246^a into contact. The trunk-release circuit through the release magnet 115^a, however, is not completed, because it is open at the point 110 between the ringer relay springs 276 and 277, and it requires the simultaneous energization of the rotary line relays 261 and 262 and de-energization of the ringer relay 286 to establish said circuit. The passage of the 115 connector side switch P to third position accomplishes still another result, namely the energization of the line-cut-off relay 307 (Fig. 6) from ground G^{18} through the 120 winding of said cut-off relay to the vertical normal conductor 282, thence to the vertical line wiper 272 of the connector B, side switch contact point 298, side switch wiper 296, ringer relay springs 292 and 294 to the 125 vertical back-bridge retardation-coil 308 to the battery lead 138, and through battery B' to ground G' . As soon as the cut-off relay 307 energizes, the armatures 309 and 310 then pull up and prevent the establishment 130 of the usual circuit through the line signal

relay 311 between the ground G^1 at the relay 307 and the non-grounded terminal of battery B^2 . After the cut-off relay 307 is thus operated, the subscriber at the substation #2220 is unable to operate the line signal relay 311 to flash the lamp 312 for signaling the operator at G. This, of course, is as it should be. The connector side switch having passed to third position 10 and accomplished the above operations, the calling subscriber then proceeds to signal the desired subscriber.

To signal, the calling subscriber presses his signaling button 31, with the result that 15 the spring 32 is separated from the contact 33; and the circuit for providing the transmitter 8 with talking battery current is opened at that point, and the vertical and rotary line relays 261 and 262 of the connector B de-energize temporarily. The said 20 spring finally engages the grounded spring 34, whereby the vertical line conductor 75 is grounded, with the result that the vertical line relay 261 of the connector is immediately energized. The energizing circuit extends from ground G^1 to the vertical line conductor 75, thence over known circuits to the vertical line relay 261 and through the winding 162 of the differential relay 163 to battery 25 lead 138, and through battery B' to ground G' . The energization of the vertical line relay 261 is of no significance, but the energization of the differential relay at this time breaks the energizing circuit of the ringer 30 relay 286, which, as described, comprises the differential relay springs 288 and 289. As soon as the ringer relay 286 permits the 35 springs 292 and 293 to return to normal position the said springs fall into normal engagement with the springs 313 and 314, whereby the ringer generator 123 is bridged across the normal conductors 282 and 283 for signaling the desired manual subscriber. The circuit established from the generator 40 123 through the bell at the substation #2220 is as follows: From the ringer generator 123 to the ringer relay springs 314 and 293, side switch wiper 297, contact point 299, rotary line wiper 273, rotary normal conductor 283 to the contact point 315, armature 310, tip line conductor 316, condenser 317, contact point 318, switch-hook 319, contact point 320, ringer 321, sleeve conductor 322, armature 323, contact 323, vertical normal conductor 282, vertical line wiper 272 of the connector B, contact point 298, side switch wiper 296, ringer relay springs 292 and 313 to the ringer generator 123. It will be understood that as soon as the ringer relay de-energizes 45 the local circuit for magnetizing the line-cut-off relay 307 (Fig. 6) is broken, when the ringer relay springs 292 and 294 separate. It will be noticed, however, that one side of the ringer generator 123 is connected 50 to battery B' through a resistance-coil; and

although the said energizing circuit for the said relay 307 is broken, a new circuit is established through said resistance-coil so that the relay 307 is kept pulled up during the time the subscriber is signaling. As soon 55 as the ringer relay 286 falls back to normal condition, when the subscriber ceases pressing his signaling button, the original energizing circuit is restored. When the subscriber at substation #2220 responds after 60 hearing the signal he removes his receiver 324 from the switch-hook 319 and establishes a charging circuit through the transmitter 325, supplying the said transmitter with talking current, from ground G^1 at the connector side switch B to the contact point 285, side switch wiper 284, back-release relay 326, side switch contact point 299, rotary line wiper 273, rotary normal conductor 283, contact point 315 of the line relay 307 (Fig. 6), 65 armature 310, line conductor 316, retardation-coil 327, switch-hook 319, line conductor 322, cut-off-relay armature 309, contact point 323, vertical normal conductor 282, vertical line wiper 272 of the connector B, 70 contact point 298, side switch wiper 296, ringer relay springs 292 and 294 to the retardation-coil 308, thence to battery lead 138 and through battery B' to ground G' . It 75 will be evident, therefore, that the jack sleeve 328 (Fig. 6) is connected through the retardation-coil 308 of the connector, through the non-grounded terminal of battery B' ; and if the tip conductor 329 of the cord circuit 80 G , which is connected to the ground terminal G^2 , is applied to the sleeve 328 by the operator, or rather to the sleeve of one of the multiple jacks, she receives a busy click in the usual and well known manner from the ground terminal G^2 through the retardation coil 308 to the non-grounded terminal of battery B' to ground G' . It will be 85 understood that the calling and called subscribers H and M, after being connected, may converse over a circuit clearly shown by the heavy conductors (Figs. 5 and 6) that extend from the substation M to the substation H. After the subscribers are through talking they may hang up their receivers with the following results: When the called 90 subscriber hangs up his receiver, if he does so before the calling subscriber hangs up, he destroys the circuit for supplying the transmitter 325 with talking current; if he does not release at once, when the talking apparatus is released, as will presently be described, the talking current will be removed from said transmitter as soon as the connector-switch B is released and, therefore, 95 when the line wipers 272 and 273 of the connector-switch B disengage from the normal conductors 282 and 283. The release from the manual subscriber 100 #2220 may be initiated by the calling subscriber, either before or after the called sub- 105

scriber has answered, by hanging up his receiver 2 and grounding the vertical and rotary line conductors 75 and 76 simultaneously, with the result that the windings of 5 the rotary line relay 262 and winding 275 of the differential relay 163 are short-circuited through ground between the substation ground G⁴ and the ringer relay ground G¹⁷ over circuits that are now understood. As 10 a result the differential relay 163, like the differential relay 119 of the connector C, energizes and destroys the energizing circuit through the ringer relay 286, the energizing circuit for which ringer relay, it will be 15 understood, comprises the differential relay springs 288 and 289. As soon as the ringer relay de-energizes, the ringer relay spring 276 leaves the ground spring 306 and returns to engagement with the spring 277 that 20 constitutes the non-grounded terminal of the battery B'. Although the rotary line relay 262 de-energizes for an instant it is re-energized as soon as the ringer relay springs 276 and 277 engage; and the trunk-release 25 springs 245^a and 246^a, after having separated for a moment, are again brought into contact and held there. The differential relay 163 is reinforced and the ringer relay 286 is thus maintained de-energized. A trunk-release circuit is then established, comprising 30 the release magnet 115^a and the back-release relay 179 of the second-selector E. This energizing circuit extends from ground G²¹ to the side switch wiper 180, and from the back-release relay 179 of the second-selector 35 F' to the private wiper 170, thence to the trunk-release conductor 183, to the trunk-release springs 245^a and 246^a, to the release magnet 115^a, through the ringer relay springs 40 276 and 277 to the battery lead 138, and through battery B' to ground G'. As soon as the connector release magnet 115^a energizes, the connector switch-shaft and side switch are released and the line wipers 272 45 and 273 are disconnected from the normal conductors 282 and 283, whereby the energizing circuit through the line-cut-off relay 307 is destroyed. Of course, the restoration of the side switch destroys the energizing 50 circuit to the ringer relay 286, and talking current is removed from the calling subscriber's line. The remaining release operations of the switches are the same as those heretofore described.

55 An automatic call to the sub-central may be made if the subscriber at substation H wishes to call any of the subscribers at the sub-central office (Fig. 8). In order to do so the subscriber must operate his dial in accordance with the digit 9, with the arrangement herein shown, so as to raise the switch-shaft and carry the wipers 43, 44 and 45 into engagement with some trunk line leading from the ninth level to a repeater F 60 (Fig. 5). As soon as the side switch of the selector A passes to third position a circuit is closed through the line relays 124 and 125 and the windings of the differential relay 126 at the repeater F and through the transmitter 8 at the substation H, whereby 70 the said transmitter is provided with current for talking purposes. The circuit may be traced from ground G²² at the repeater F through the differential relay springs 330 and 331, winding 127 of the 75 differential relay 126, vertical line relay 124, vertical trunk conductor 332, vertical line wiper 43 of the selector A, contact point 65 of the side switch N, vertical line conductor 75, through the transmitter 8, primary winding 11 to the rotary line conductor 76, thence to the side switch wiper 50 of the selector A, through the contact point 66, rotary line wiper 44, rotary trunk conductor 333, vertical line relay 125, winding 128 of the differential relay 126 to the battery lead 138, and through battery B' to ground G'. This current, furthermore, energizes the line relays 124 and 125, causing the former to press the springs 334 and 335 into engagement and the latter to bring the springs 336 and 337 into engagement. A circuit is in turn established, when the springs 334 and 335 press into contact, from the ground terminal G²³ through the relay 130 and springs 335 and 334 to the vertical trunk conductor 338. Another circuit is established from the rotary trunk conductor 339 at the repeater F through the line relay springs 336 and 337, and through 80 the relay 129 to the battery lead 138, thence through battery B' to ground G'. This last circuit upon being established causes the energization of the supervisory relay 340 at the cord circuit D (Fig. 8) from ground 85 G²⁴ at the cord circuit D through the relay 340 and winding 341 of the repeating coil to the rotary trunk conductor 339, thence through the line relay springs 336 and 337, through the relay 129 to the battery lead 138, and through battery B' to ground G'. At the same time it will be noticed that a circuit is closed from ground G²² through the differential relay springs 330 and 331, through the auxiliary relay springs 342 and 343, through the relay 131 and through the line relay springs 336 and 337 and the relay 129 to the battery lead 138, and through battery B' to ground G'. However, since the relay 129 energizes in series with the supervisory relay at the cord circuit D the circuit 95 through the relay 131 is destroyed when the relay 129 separates the relay springs 342 and 343. The object in thus giving the relay 129 supervision over the relay 131 is to maintain the said relay 131 disconnected from the line to prevent the line from being noisy. The relay 340 at the cord circuit D upon energizing attracts the armature 344 into engagement with the contact point 345, 100 105 110 115 120 125 130

whereby the supervisory lamps 346 and 347 become lighted, the former through the circuit extending from ground G^{24} through the armature 344, contact point 345, contact point 348, armature 349, conductor 350, armature 352, contact point 351, lamp 346 to the battery B^3 and through said battery to ground G^3 . Through the other lamp the circuit extends from ground G^{24} to the armature 344, thence through the contact point 345 to the contact point 353, armature 354 to the lamp 347, and through said lamp to battery B^3 and to ground G^3 . The operator upon noticing the signal will understand that someone is calling from the trunk line and operate her key to establish a talking circuit with the calling subscriber. The receiver 355 of the cord circuit D, together with its secondary winding 356, are connected in series with the repeater windings 357 and 358 as follows: from the winding 357 to the conductor 359, spring 360 of the key Q, contact point 361, receiver 355, secondary winding 356 of the induction-coil 362, condenser 363, contact point 364, spring 365, conductor 366 to the repeater winding 358, thence through the condenser 367 back to the winding 357. Of course, the operator in talking into the transmitter 368, which is in series with a battery (not shown) and the primary winding 369 of the induction-coil 362, sends voice-currents over the above described circuit that are induced in the repeater windings 370 and 341. These induced voice-currents reach the calling subscriber at substation H over the following path: from the vertical trunk conductor 338 to the condenser 132 at the repeater F (Fig. 5), thence through the vertical trunk conductor 332, vertical line wiper 43 of the selector A, side switch contact point 65, side switch wiper 49, vertical line conductor 75, through the transmitter 8 and primary winding 11 of the induction-coil 10 back to the rotary line conductor 76 and side switch wiper 50 of the selector A, contact point 66, rotary line wiper 44, rotary trunk conductor 333, condenser 133 at the repeater F and through said condenser to the rotary trunk conductor 339, thence through the repeater winding 341, condenser 402, repeater winding 370 and again to the vertical trunk conductor 338. The subscriber at the substation H will then give the order to the line operator at the cord circuit D. If the substation K is called the operator inserts the plug g into the jack c for establishing the connection. As soon as the said plug is inserted into the said jack the cut-off relay 371 energizes, and also the line relay 372, energizing both in series. The energizing circuit extends from ground G^{25} through the winding 373 of the said relay 372 to the tip spring 374 of the jack c, thence to the tip 375 of the plug g to the spring 376 of the ringing key R, contact point 377, spring 360 of the operator's key Q, conductor 378 to the cut-off relay 371, thence through said relay to the battery B^3 and to ground G^3 . When the cut-off relay 371 energizes it cuts out the supervisory lamp 347 when it 70 attracts the armature 354, which armature, as previously described, is in the circuit of the said lamp 347. The supervisory lamp 346, however, does not go out, since the armature 349 passes into engagement with another grounded contact 379. The supervisory lamp 346 is retained lighted by a flow of current from ground G^{26} to the contact point 379, armature 349, armature 352, contact point 351 and lamp 346 to the battery 80 B^3 and to ground G^3 . The operator then presses her ringing key R and sends current out to the substation K from the generator 380 by pressing the springs 376 and 381 onto the terminals of the ringing generator 380. 85 Of course, the lamp 347 again flashes up for an instant while the circuit is open at the ringing key R, but it will go out again just as soon as the said key is thrown back into normal position. When the cut-off relay 372 is energized the armature 382 is attracted and carried into engagement with the contact point 383, whereby, as soon as the called subscriber removes his receiver from the hook, the supervisory relay 384 is energized over a circuit extending from ground G^{25} of the cut-off relay 372 through the winding 373 to the sleeve line conductor 385, through the transmitter 386, primary winding 387 of the induction-coil 388, switch-hook 389, line conductor 390 to the jack sleeve spring 391, plug sleeve 392, spring 381, contact point 393, conductors 394 and 395 to the relay 384, thence to battery B^3 and through said battery to ground G^3 . 90 Therefore, the same current that energizes the called subscriber's transmitter energizes the supervisory relay 384, which latter in turn by attracting its armature 396 energizes the supervisory relay 397 from ground G^{27} to the armature 396, contact point 398, supervisory relay 397 to the battery B^3 and through said battery to ground G^3 . Said relay attracts its armature 352, destroying the circuit through the front supervisory lamp 346, which lamp then, of course, goes out, indicating to the operator that the subscriber has answered. It will be noticed that the armature 352 when attracted is carried into engagement with the contact point 399, which latter is, of course, grounded at the time, as explained. The object of this construction will be described. When the supervisor relay 384 energizes it also attracts the armature 400, which armature is brought into engagement with the contact point 401, short-circuiting the condenser 402 and closing an energizing circuit through the coils 120 125 129 and 130 at the repeater F over the fol. 130

lowing circuit: from the repeater ground G²³ to the coil 130, thence through said coil and through the line relay springs 335 and 334 to the vertical trunk conductor 338, 5 repeater winding 370, supervisory relay armature 400, contact point 401, repeater winding 341 to the rotary trunk conductor 339, thence through the line relay springs 336 and 337 and through the coil 129 to 10 the battery lead 138 and to battery B', and through said battery to ground G'. The calling and called subscribers H and K, when thus connected may converse over the following circuits: The voice-currents of 15 the calling subscriber pass through the circuit previously described that comprises the repeating coil windings 341 and 370, the only difference being that since the supervisory relay 384 is energized the current, instead of passing through the condenser 402, passes through the armature 400 to the contact point 401. The voice-currents from substation H are in turn induced in the primary windings 357 and 358, from 20 whence they pass to the substation K over the following circuit: from the repeater winding 357 to the conductor 359, operator's key spring 360 to the ringing key contact point 377, spring 376, plug tip 375, 25 tip spring 374, line conductor 385 to the transmitter 386 at the substation K, through the primary winding 387 of the induction-coil 388 to the line conductor 390 and back to the sleeve spring 391 of the jack c, to 30 the plug sleeve 392, spring 381, contact point 393, spring 365, conductor 366 and to the repeating coil 358. Through the medium of these inductively connected circuits the two subscribers may communicate with 35 each other. After the subscribers are through talking, if the automatic subscriber H releases he grounds the vertical and rotary line conductors 75 and 76 simultaneously, short-circuiting the vertical line relay 124 and the winding 127 of the differential relay 126 of the repeater F between the ground terminals G²² at the repeater F and G⁴ at the substation H. The result is that the differential relay 126 energizes, 40 carrying the differential relay spring 331 away from the ground spring 330 and into electrical connection with the springs 403 and 404. The energizing circuit for the differential relay 126 extends from the substation ground G⁴ to the rotary line conductor 76, side switch wiper 50 of the selector A, rotary line wiper 44, rotary trunk conductor 333, rotary line relay 125, winding 128 of the differential relay 126 to 45 the battery lead 138, and through battery B' to ground G'. As soon as the differential relay pulls up, as described, a new circuit is established through the short-circuited line relay 124 and winding 127 of the differential relay 126, permitting current to flow in a reverse direction from the substation ground G⁴ to the vertical line relay 124 of the repeater F, thence through the winding 127 of the differential relay 126, through the springs 331, 403 and 404 and resistance-coil 405 to the battery lead 138 and through battery B' to ground G'. The result is that the trunk-release springs 406 and 407 are brought into engagement at the time when the differential relay 126 is 50 energized and, therefore, when the trunk-release spring 407 is connected with the resistance-coil 405, with the result that the back-release relay 72 of the first-selector A energizes by current flowing from ground G⁷ at the selector side switch to the side switch wiper 48, thence through the back-release relay 72 to the private wiper 45, private trunk conductor 408, trunk-release springs 406 and 407, differential relay 55 springs 403 and 404, resistance-coil 405 to the battery lead 138 and through battery B' to ground G'. The back-release relay 72, therefore, energizes and in turn causes the energization of the release magnet 71. The energizing circuits thus described are, of course, destroyed as soon as the substation release springs 35, 36 and 37 separate, with the result that the selector-switch A is restored in a well-known manner, and the energizing circuits through the line relays 125 and 124 of the repeater F are cut off. The said line relays upon returning to normal condition permit the springs 335, 336, 60 337, 406 and 407 to regain their normal condition, whereby the magnetizing circuits through the auxiliary coils 130 and 129 are also broken, permitting the said repeater F to become fully restored. The connection, therefore, between the non-grounded terminal of battery B' and the rotary trunk conductor 339 leading to the cord circuit D is broken, and as a result the supervisory relay 340 of the said cord circuit is de-energized and the armature 344 of said relay re-engages with the contact point 409. The falling back of said armature causes the supervisory lamp 247 to light up by current from ground G²⁴ through the armature 344 to the contact point 409, thence through the contact point 410 of the relay 371 to the armature 354 and through the lamp 347 to the battery B³ to ground G³. When the operator at the cord circuit D sees the lamp 347 flash up she does not wait for any further signal, but withdraws the plug g from the jack c, thus restoring the remaining supervisory relays 371, 384 and 397 at the cord circuit D and the line relay 372. 65 A manual call to the sub-central (Fig. 8) from the subscriber L at the main exchange involves the same circuits at the cord circuit D that were involved when the automatic subscriber at substation H called the 70 75 80 85 90 95 100 105 110 115 120 125 130

subscriber K. For example, if a subscriber at substation L (Fig. 6) wishes to call the subscriber at substation K (Fig. 8) he sends in a signal to the operator at the cord circuit G by removing his receiver 411 from the switch-hook 412. The line relay 413 energizes by a flow of current from ground G²⁸ through the transmitter 414, through the coil 413 to the non-grounded terminal of battery b² and thence to ground G². The line relay 413 upon attracting its armature causes the light 415 to flash up, at which time the operator inserts the plug h into the jack a. As a result the cut-off relay 416 energizes 15 in series with the supervisory relay 417 in the usual and well-known manner by a flow of current from ground G²⁹ through the sleeve conductor to the supervisory relay 417, thence to the non-grounded terminal of battery b² to ground G². At the same time the supervisory relay 418 energizes from ground G² through the supervisory relay 418 to the tip conductor, thence through the transmitter 414 to the sleeve conductor, and through 20 the supervisory relay 417 to the non-grounded terminal of battery b². As soon as the cut-off relay 416 energizes the line relay 413 de-energizes and the lamp 415 goes out. By pressing her key the operator comes in on the 25 line, inquiring of the subscriber at substation L which number he wishes. The connecting circuit between the operator's talking set and the subscriber at substation L extends from the receiver 419 to the contact point 420, spring 421 to the tip conductor and out through the substation transmitter 414 to the sleeve conductor and to the key spring 422, contact point 423, secondary winding 424 to the receiver 419. The transmitter 425 of the operator, of course, is in 30 a local circuit as usual. Upon being informed that the substation K is desired the operator first inquires to find out if the first trunk line leading to the sub-central (Fig. 8) and leading from the jack d' is busy. She does so by striking the tip 329 of the plug i onto the sleeve conductor 426 of the jack d'. It will be remembered that while connection was established between the repeater F and 35 cord circuit D the rotary trunk conductor 339 was connected through the line relay springs 336 and 337, and through the coil 129 with the non-grounded terminal of battery B', Fig. 5. In case the trunk line leading to the cord circuit D is thus occupied at the instant that the plug tip 329 engages the sleeve 426 a circuit is established from the said non-grounded terminal of battery B' to the rotary trunk conductor 339, to the plug 40 sleeve 426, thence through the tip conductor 329, armature 427 of the supervisory relay 428, through the busy relay 429 to the ground terminal G² at the cord circuit G. The busy relay 429 then draws its armature 430 onto 45 the contact point 431 that connects with the

non-grounded terminal of battery B² through the tertiary winding 432 of the induction-coil j. The operator then receives a busy click in her ear, which will inform her that the trunk line is in use; but if she does not 50 get a busy click she inserts the plug i into the jack d', energizing the supervisory relay 340 at the cord circuit D by a flow of current from the non-grounded terminal of the battery B² at the cord circuit G, through the 55 supervisory relay 428 of the sleeve 433 of the plug i, to the sleeve 426 of the jack d', thence to the rotary trunk conductor 339 and through the supervisory relay 340 to ground G²⁴. At the same time the supervisory relay 428 at the cord circuit G energizes and the armatures 434 and 427 are carried into engagement with the contact points 435 and 436, respectively; but the supervisory lamp 437 lights up by a flow of current from ground G² at the cord circuit G, through the armature 438 of the supervisory relay 439 at the contact point 440, lamp 437, armature 434, contact point 435 to the non-grounded terminal of battery B² and to 60 ground G². When the supervisory relay 340 at the cord circuit D energizes, after the operator at the cord circuit G inserts the plug i into the jack d', the said relay attracts its armature 344, energizing the lamps 65 346 and 347 over well-known circuits from ground G²⁴ through said lamps to battery B³. The operator then comes in on the line by throwing over her key Q and connecting with the calling subscriber at substation L. 70

The talking circuit of the operator at the cord circuit D is already known, and the talking circuit leading to the subscriber L extends from the repeating coil 370, thence to the vertical trunk conductor 338 to the 75 tip spring 441 of the jack d', plug tip 329, tip conductor to the armature 427 of the supervisory relay 428, contact point 436, condenser 442, tip spring 443 to the substation L and back to the sleeve 444, condenser 445^a to the sleeve 433 and rotary trunk conductor 339, repeater coil 341, condenser 402 back to the coil 370. The subscriber then gives the order to the operator, who plugs into the jack c, establishing connection 80 with the substation K. As has already been described the supervisory relay 371 energizes in series with the cut-off relay 372 and the lamp 347 goes out; then when the subscriber K removes his receiver the supervisory relay 384 operates, energizing in turn the supervisory relay 397, which in turn causes the lamp 346 to go out. Furthermore, the relay armature 400 engages the contact point 401, establishing the energizing circuit with the supervisory relay 439 of the cord circuit G. The energizing circuit for said supervisory relay 439 extends from ground G² through the said relay 439 to 85 the contact point 436 and armature 427 of 90

the supervisory relay 428, thence out to the tip spring 441 of the jack d' , through the repeating coil winding 370 at the cord circuit D, through the armature 400, contact point 401 to the repeating coil winding 341 and back to the sleeve 426 of the jack d' , thence over the sleeve conductor through the supervisory relay 428 to the nongrounded terminal of battery B^2 . The said relay 439 upon energizing destroys the circuit through the supervisory lamp 437, permitting the said lamp to go out, which informs the operator at the cord circuit G that the called subscriber has answered. After the conversation is terminated the calling subscriber L hangs up his receiver and destroys the energizing circuit for the front supervisory relay 418 of the cord circuit G, whereby the lamp 445 is supplied with current from ground G^2 through the armature 446 and contact point 447, which are now in engagement, through the lamp 445, armature 448, contact point 449 to the non-grounded terminal of battery b^2 . The operator at the cord circuit G will then understand that the conversation has terminated and will withdraw the plugs h and i from their respective jacks. Among other results the supervisory relay 340 at the cord circuit D is de-energized, whereby the supervisory lamp 347 flashes up, indicating to the operator that the conversation has terminated, and she then withdraws the plug g from the jack c . While the connection is maintained, however, the trunk leading to the cord circuit D is made busy by a flow of current through the relay 131 at the repeater F (Fig. 5) from the non-grounded terminal of battery B^2 at the cord circuit G, and from the said battery B^2 to the rotary trunk conductor 339, thence through the relay 131, springs 343 and 342, and through the differential relay springs 331 and 330 to ground G^{22} . Said relay 131 then forces the springs 449 and 450 into contact, connecting in turn the trunk-release conductor 408 with ground G^{22} and as a result establishing a guarding potential at a corresponding private bank contact in the selector banks, whereby no selector will be able to come in on the trunk line while it is in use. This guarding potential is, of course, removed as soon as the operator removes the plug i from the jack d' .

55 A call from the sub-central to the main-central office may be made to either a manual or an automatic subscriber by way of the trunking operator at the cord circuit D. The subscriber K, for instance, if he wishes to call the subscriber M, removes his receiver from his switch-hook and energizes the line signal relay 450 by a flow of current from ground G^{25} through the winding 373 of the cut-off relay 372 to the transmitter 386, thence through said transmitter and armature 382 of the cut-off relay 372, through the winding 351 of the said cut-off relay 372, thence through the line relay 450 to the battery B^3 and to ground G^3 . The relay 450 upon energizing causes the signal lamp 452 to light in front of the cord circuit D' . The operator at said cord circuit then comes in on the line in the usual manner, and upon ascertaining the number the subscriber at substation K desires she presses an order key 453 that signals the operator at the cord circuit D by causing the lamp 454 to light up. The said operator at the cord circuit D in turn presses the button 455, bridging her talking set in multiple with the talking set of the operator at the cord circuit D' , and receiving the order from the latter operator. The operator at the cord circuit D then inserts the plug g in the jack c and at the same time presses an order wire key 456 that signals the operator at the cord circuit G by causing the lamp 457 to light up. The operator at the said cord circuit G presses the button 458 and comes in on the line and receives the order. If told to come in on the trunk that terminates at the jack d' she inserts the plug h in the jack d' and in turn inserts the calling plug i in the jack k of the line that leads to the substation M. It will be understood, of course, that as soon as the answering plug of the cord circuit D' is inserted into the jack 1 the cut-off relay 372 energizes and is retained energized when the operator at the cord circuit D inserts her plug g into the multiple jack c . The cut-off relay 372 does not energize when the subscriber K first removes his receiver, because the said relay 372 is differentially wound; but when the plug g is inserted in the jack c , the said cut-off relay 372 energizes in series with the supervisory relay 371 over circuits that have been described. When the said relay 371 pulls up, and since the supervisory relay 340 is de-energized, both the lamps 347 and 346 light up by a flow of current from ground G^{24} through the armature 344 and contact point 345 to the lamps 346 and 347, to the non-grounded terminal of battery B^3 and through said battery to ground G^3 . However, since just at about the same time the supervisory relay 384 energizes over the sleeve conductor, through the transmitter 386 to the ground G^{25} of the cut-off relay, the supervisory relay 397 is in turn energized, extinguishing the supervisory lamp 346, leaving only the lamp 347 illuminated. The supervisory relay 384, by attracting the armature 400 onto the contact point 401, connects the vertical and rotary trunk conductors 338 and 339 through the repeating coil windings 370 and 341, preparatory to the subsequent establishment of another energizing circuit. As soon as the operator at the cord circuit G inserts the plug h in the jack d' the su-

supervisory relay 340 at the cord circuit D energizes, and also the supervisory relays 417 and 418 at the cord circuit G. The energizing circuit for the relay 340 and for the supervisory relay 417 in series therewith extends from ground G^{24} at the cord circuit D through the relay 340 to the rotary trunk conductor 339 and to the sleeve 426 of the jack d' , thence to the sleeve 459 of the plug h to the supervisory relay 417 and to battery B^2 . The energizing circuit for the supervisory relay 418 extends from ground G^2 at the cord circuit G through the plug tip conductor 460 to the tip spring 441 of the jack d' , thence to the vertical trunk conductor 338, repeater winding 370, armature 400 and contact point 401 to the rotary trunk conductor 339, and thence to the non-grounded terminal of battery B^2 .
 20 When the supervisory relay 340 of the cord circuit D energizes, the lamp 347 is extinguished, and the operator at the cord circuit D will understand that the operator at the cord circuit G has plugged in on the line. Before inserting the plug i into the jack k the operator strikes the sleeve 328 with the plug tip 329, and if the trunk line comprising the conductors 282 and 283 that terminate in the bank terminals of the connector B is busy, the operator will get a busy test, as previously described, if the sleeve 328 is connected to the non-grounded terminal of battery B' , Fig. 5. The connection will extend from the sleeve 328 to the vertical trunk conductor 282, vertical line wiper 272 of the connector B, side switch contact point 298, ringer relay springs 292 and 294 to the back-bridge retardation coil 308, thence to the battery lead 138 and through battery B' to ground G' . Of course if no busy test signal is received the operator plugs into the jack k , energizing the supervisory and cut-off relays 428 and 307 from the cut-off relay ground G^{18} through the cut-off relay 307 to the sleeve 328 over the sleeve conductor, through the supervisory relay 428 to the non-grounded terminal of battery B^2 to ground G^2 . Said relay then attracts its armatures 427 and 424, causing the latter to engage the contact point 433, establishing a circuit through the lamp 437 for energizing said lamp. The circuit through said lamp has already been described. The operator at the cord circuit G then operates his ringer key T, pressing the springs 461 and 462 onto the contact points 463 and 464, thus sending a ringing current out to the called subscriber's line from the ringer generator 123 (Figs. 3 and 5) to the conductor 465, contact point 463, tip conductor 329, armature 310 of the cut-off relay 307, tip conductor 316, through the ringer 321 to the sleeve conductor 322, armature 309 of the relay 307 to the sleeve 328 and sleeve conductor 433,

spring 462 and contact point 464 to conductor 465 and back to the generator ground G^{20} , thence to the generator 123 again. It will be understood, of course, that since the cut-off relay 307 is energized the armatures 309 and 310 are attracted. When the subscriber at the substation M answers, the supervisory relay 439 is then connected in series with the supervisory relay 428 and becomes energized. The energizing current 75 passes from ground G^2 through the said relay 439, through the contact point 436 and armature 427 of the relay 428 to the tip conductor 329, thence through the armature 310, substation transmitter 325 back to the armature 309, and thence through the relay 428 to the non-grounded terminal of battery B^2 . As soon as the relay 439 energizes, the supervisory lamp 437 is deprived of energizing current and the armature 438 leaves the contact point 440. The operator will then understand that the subscriber has answered. After the subscribers are through talking, if the subscriber at the substation M hangs up his receiver he destroys the energizing circuit just described for the supervisory relay 439 and restores the circuit through the lamp 437, thus signaling the operator that the line is no longer in use. The operator at the cord circuit G then withdraws the plugs i and h from the respective jacks k and d' , causing the energizing circuit through the supervisory relay 340 at the cord circuit D to be destroyed. When the said relay de-energizes the armature 344 falls back onto the contact 409, re-establishing the circuit through the lamp 347, which lamp, as soon as it flashes up, gives the operator the signal to disconnect. Upon disconnecting the cut-off relay 372 of the subscriber K is, of course, restored, and also the cut-off relay 307 of the subscriber M when the plug i leaves the jack k . It will be understood that the cord circuit D' is a well-known cord circuit, and that the manual subscribers at the sub-central exchange (Fig. 8) may call each other through the medium of cord circuits like the cord circuit D'—for instance, the subscriber K may call the subscriber J in the usual manner. Furthermore, in Figure 6 the manual subscribers may call each other through the medium of cord circuits like the cord circuit G—for instance, the subscriber L may call the subscriber M by methods that are well understood through the circuits that have been disclosed.
 105 If the manual subscriber at substation K calls the automatic subscriber at substation H the operator at the cord circuit G, after receiving the order from the trunking operator at D, will insert the plug i in the jack b instead of the jack k . Upon inserting the plug i in the jack b an energizing circuit is 110 established through the supervisory relay 115

428 of the cord circuit G, in series with the private normal relay 74 at the selector A, from the non-grounded terminal of battery B' at the cord circuit G to the sleeve conductor 433, thence to the sleeve 160, conductor 78, private normal relay 74, side switch wiper 46 to the ground terminal G'. The supervisory relay 428 will, of course, energize, and the private normal relay 74 also, the former causing the lamp 437 to light and the latter pressing the springs 476 and 477 into engagement, thus placing a guarding potential at the private normal conductor 159 to prevent another automatic subscriber from calling in and interfering with the connection. Not only is the guarding potential established at the private normal conductor 159, but an energizing current is sent through the line switching relay 73 when the said springs 476 and 477 are pressed into contact. The current flows from ground G' through the said springs 477 and 476, side switch wiper 48, contact point 54, line switching relay 73 to the battery lead 138, and through battery B' to ground G'. The line switching relay, therefore, energizes, switching the springs 135 and 145 onto the springs 468 and 469, and thus connecting the subscriber's line conductors 75 and 76 with the conductors 77 and 78. The operator then upon pressing the ringer key T sends ringing current out to the desired subscriber's line conductors 75 and 76 by way of the jack conductors 77 and 78, thus signaling the subscriber at substation H. As soon as the subscriber removes his receiver 2 from the switch-hook 3 the circuit is closed between the vertical and rotary line conductors 75 and 76 and, therefore, between the jack conductors 77 and 78, through the transmitter 8; and current is also sent through the supervisory relay 439 for energizing said relay, whereby the armature 438, upon being attracted, disconnects the signaling lamp 437, as already explained. Said lamp upon going out indicates to the operator that the subscriber has answered. The subscriber at substation H, upon hanging up his receiver when the conversation is over, again destroys the circuit through the said supervisory relay 439, giving the operator at the cord circuit G a disconnect signal; she then withdraws the plugs i and h from their respective jacks. When the plug h is withdrawn from the jack d' the operator at the cord circuit D is given the disconnect signal, as already explained, and she will in turn disconnect as before.

If the manual subscriber at substation L wishes to call the automatic subscriber at substation H it will be clear that the operation of the cord circuit G will be the same as the operation of said cord circuit described when the manual subscriber K calls the automatic subscriber H, the only differ-

ence being that the plug h is inserted in the jack a instead of in the jack d'.

Busy lines may be taken care of in this system by guarding potentials. It has been described how the busy test is given the operator at the cord circuit G if the manual subscribers at the sub-exchange (Fig. 8) try to call the manual subscribers at the main exchange (Fig. 6), or if the manual subscribers at the sub-exchange try to call the automatic subscribers at the main exchange. It will also be understood that the busy signal, when one manual subscriber tries to call another manual subscriber at the sub-exchange (Fig. 8), since standard circuits are employed, is given over circuits that are well known. Also, when the manual subscribers at the main exchange (Fig. 6) wish to call each other, the method of making the busy test has been explained. It has also been pointed out how a guarding potential is established at the trunk line to which the repeater F is allotted to prevent automatic switches, such as the selector A, from coming in and seizing the trunk.

It remains now to describe the effect of the busy line in case the automatic subscriber H tries to call the automatic subscriber #6220, and also when the automatic subscriber H tries to call the manual subscriber M. It has been explained that if a line is busy when the automatic subscriber grounds his rotary line conductor 76 at the end of the last digit for the connector, said switch will be released for the following reasons: Referring to Figs. 2 and 7, after the wipers have been rotated into engagement with the desired line the private wiper 100 is carried into engagement with a grounded contact if the line is busy; then when the rotary line conductor 76 is grounded the connector rotary line relay 111 is energized, and in turn the private magnet 114 is energized, and the private springs 470 and 471 are pressed into contact at the same time that the differential relay 119 is energized. As a result a magnetizing current is sent through the release magnet 115 over the following circuit: from the grounded private contact point to the private wiper 100, side switch wiper 232, conductor 472, private springs 470 and 471 to the release magnet 115, thence over the conductor 473 and differential relay springs 220 and 218 to the battery lead 138, and through battery B' to ground G'. The release magnet then attracts its armature 247, releasing the side switch and switch-shaft, breaking the release circuit when the private wiper 100 leaves the grounded contact point. When the subscriber presses his signaling button, after he thinks he has established connection, and grounds his vertical line conductor 75, as previously described, operating the vertical line relay 110 over well-known circuits, the vertical mag-

net 112 is energized, which latter then operates to raise the switch-shaft 97. The switch-shaft upon rising permits the off-normal springs 108 and 109 to come into contact, establishing a busy signalling current from the busy machine U to the conductor 474, off-normal spring 109, thence through the spring 108 to the side switch contact point 475, side switch wiper 215, ringer relay springs 214 and 213 to the condenser 212, thence to the subscriber's rotary line conductor 76, over previously described circuits, through the primary winding 11 and transmitter 8 at the substation and back to the vertical line conductor 75, thence to the vertical line relay 110 at the connector C and through the differential winding 121 to the battery lead 138, and thence again to the busy machine. The subscriber upon hearing the busy signal will hang up his receiver and thereby ground the line conductors simultaneously, energizing the vertical and rotary line relays 110 and 111 of the connector C, as previously described, causing the trunk-release springs 245 and 246 to come in contact, and at the same time energizing the differential relay 119. The result is that the release magnet 115 is energized in series with the back-release relay 179 of the second-selector E, as previously explained, which relay in turn causes the energizing of the back-release relay 72 of the first-selector A over circuits that are already known. Both said back-release relays produce the energizing of the release magnets of their respective switches, namely the release magnets 95 and 71. As soon as the subscriber's switch-hook descends sufficiently all of the release circuits are destroyed and the switches are fully restored. If the subscriber at substation H attempts to establish connection with the substation M while the manual subscriber I is connected with the manual subscriber M, a guarding potential will be found at the rotary normal conductor 283 of the connector B, appearing there through the supervisory relay 439 and from the grounded terminal of battery B² of the cord circuit G, Fig. 6. At the instant that the calling subscriber grounds his rotary line conductor at the end of the calling of the last digit, the rotary line wiper 273 is then in engagement with the rotary normal conductor 283, having been previously rotated there, as described. Therefore, when the rotary line relay 262 energizes it in turn, energizes the private magnet 279, as already explained, bringing together the private springs 475' and 476'. The primary effect of this operation is to energize the release relay 326 of the connector B. The energizing current flows from ground G² at the cord circuit G through the supervisory relay 439, contact point 436 and armature 427 of the supervisory relay 428 to the tip conductor 329 of the plug i, thence to the rotary normal conductor 283, rotary line wiper 273, contact point 299, release relay 326 to the side switch wiper 284, contact point 477', private springs 475' and 476', through the release magnet 115^a, through the ringer relay springs 276 and 277 to the battery lead 138, and through battery B' to ground G'. The release relay 326, therefore, pulls up by being of much higher resistance than the release magnet 115^a. The said release magnet does not energize, but as soon as the release relay operates to carry the springs 478 and 479 into engagement another circuit is established through the release magnet 115^a for operating the same. The said circuit extends from ground G³¹ through the release relay springs 478 and 479 to the private springs 475' and 476', thence through the release magnet 115^a and through the ringer relay springs 276 and 277 to the battery lead 138, and through battery B' to ground G'. The release magnet 115^a then attracts its armature and restores the connector switch shaft and side switch. The release circuit is destroyed as soon as the private magnet 279 permits the springs 475' and 476' to disengage. The subscriber then, thinking that he has established connection, presses his signaling button and grounds the vertical line conductor 75, energizing in turn the vertical line relay 261 of the connector B. Said relay in turn operates the vertical magnet 266, raising the shaft 271 and causing the springs 479' and 480 to come into contact and thereby close a busy signalling circuit from the busy machine U to the side switch wiper 481 of the side switch P, contact point 482, switch shaft springs 479' and 480 to the condenser 303, thence to the subscriber's rotary line conductor 76, through the primary winding 11 and transmitter 8 at the substation H to the vertical line conductor 75, thence to the vertical line relay 261 of the connector B and through the differential winding 162 to the battery lead 138 and back again to the busy machine. The subscriber upon hearing the busy signal restores his receiver, grounds his line conductors simultaneously, and as a result energizes the vertical and rotary line relays 261 and 262 of the connector B simultaneously; thus bringing the trunk-release springs 245^a and 246^a into contact, whereby a release circuit is established through the release magnet 115^a of the connector B and back-release relay 179 of the second-selector E in series. Said relay and magnet energize with the usual result, the latter restoring the connector-switch and the former energizing the release magnet 95 of the second-selector E and the back-release relay 72 of the first-selector A. The release relay 72 in turn causes the energization of the release mag.

net 71, and when the subscriber's switch-hook descends sufficiently all of the release circuits are destroyed, as already explained, and the switches return to their normal positions.

As shown, my invention embodies principles and improvements for a highly efficient telephone system of a complex character that comprises a main central office to which may be connected suitable sub-central stations. It involves a combined automatic and manual main exchange and a sub-central manual exchange, but it will be evident that there may also be a sub-central automatic exchange if desired. Furthermore, it is not essential that the main central offices be combined automatic and manual, as they may be purely automatic if desired or they may be purely manual. The sub-central stations may be combined automatic and manual if desired and not necessarily purely automatic or purely manual. It will be understood that with the arrangement herein shown all automatic subscribers' lines at the main central office terminate in jacks such as the jacks *b* and *f*, all of which are grouped in any suitable or approved manner known to the telephone art. The manual subscribers' line jacks such as the jacks *a* and *h* of the substations *L* and *M* are provided with normal conductors, such as the normal conductors 483 and 484 and 282 and 283 that lead to the connector banks, by means of which conductors the automatic subscribers may establish connection automatically with the manual subscribers.

In Fig. 9 is shown the method of cross-connecting between the first-selector bank contacts and the operators' trunk jacks, Fig. 6. As shown, the trunking jack *d'* connects with the same trunk line that the trunk terminal *e¹⁰* connects with. It will be noticed, as indicated in Fig. 9, that the connection between the selector bank terminal *e¹⁰* and trunk conductors 338 and 339 is established through the repeater *F*. In the description of circuits it was explained how the automatic subscriber at substation *H* in calling a subscriber at the sub-exchange (Fig. 8) operated his selector *A* to carry the wipers to the ninth level and then into engagement with the trunk line leading to the repeater *F*; therefore, with the construction shown, it is obvious that the wipers of the selector *A* are rotated into engagement with the tenth trunk line terminal, it being assumed that the other terminals *e*, *e'*, *e²*, etc., are busy. The wipers upon engaging with the terminal *e¹⁰* established a connection between the substation *H* and the repeater *F*, as already explained. The order wire keys that have been shown in Figs. 6 and 8 may be of any known or approved type.

In the repeater *F* the windings of the various coils there used may have the following

resistances: The line relays 124 and 125 one hundred ohms each; the windings 127 and 128 of the differential relay 126 two hundred and fifty ohms each; the coils 130 and 129 five hundred ohms each, and the relay 131 thirteen hundred ohms. These resistances have been found to give good results, but other resistances may be used if desired.

From the foregoing it will be seen that I provide a system affording service between automatic and manual subscribers, and that electric current for talking purposes is supplied to both manual and automatic subscribers from a common battery or batteries located at a central point or points. Subscribers of one class can call subscribers of the other class, a calling automatic subscriber always getting the connection automatically, and a calling manual subscriber always getting the connection manually, regardless of whether the called line leads to an automatic or manual subscriber. In all cases called lines are made busy and protected against improper seizure by either automatic or manual subscribers, and calling lines are also made busy and protected against improper seizure by either automatic or manual subscribers. This is all true, of course, when service is given between subscribers at the main exchange or central station; but when service is to be extended between the subscribers of the central station and the subscribers of a sub-central station, such as described, then it will be seen that connections are obtained by the use of both automatic and manual apparatus, in the manner described.

It will be seen that the system to which my invention relates includes switches, such as selectors and connectors, having one motion to select groups and another motion to connect with a line in any selected group. In this way the exchange may be divided and subdivided as many times as is necessary, depending upon the size or ultimate capacity of the exchange—that is to say, depending upon the number of digits employed for each subscriber's number, it being observed that with the arrangement shown each automatic subscriber's number has four digits. The manual subscribers may, of course, have numbers involving the same or a different number of digits—that is, some may have one digit, others two, and others three or four, as is usual in manual exchanges. In making a call through a connector, however, the calling subscriber first selects the thousands division of the exchange in which the called subscriber's number is found, then the one-hundred subdivision thereof, and then the tens and finally the units, as previously explained. Each numerical switch, such as a selector or a connector, involves one or more wipers having a vertical motion to select levels or groups,

and then a rotary motion to connect with a line in the selected group. The line is seized by the rotary motion may, of course, be either a trunk line or a subscriber's line, depending upon whether the switch is a selector or a connector.

What I claim as my invention is:—

1. In a telephone exchange system, the combination of a subscriber's line, trunk lines, an automatic trunk-selecting switch, means by which said switch is controlled over the line, a spring jack allotted to said line, an operator's connecting cord provided with a plug adapted for insertion in said jack, a subscriber's telephone, and a centralized source of talking current connected for supplying current over the subscriber's line to charge said telephone.

2. In a telephone exchange system, the combination of a subscriber's line, trunk lines, an automatic trunk-selecting switch, means for transmitting electrical impulses over said line to control the operations of said switch, an automatic connecting switch for making connection with said line, manual switchboard apparatus for making connection with said line, whereby said line may call automatically and be called either automatically or manually, a subscriber's telephone, and a centralized source of talking current connected for supplying current over the subscriber's line to charge said telephone.

3. In a telephone exchange system, the combination of a subscriber's line, trunk lines, an individual trunk-selecting switch for said subscriber's line, means by which the subscriber controls the said switch to select an idle trunk line, a plurality of automatic connector switches each provided with a multiple terminal of said subscriber's line, a plurality of multiple jacks allotted to said line, a subscriber's telephone, and a centralized source of talking current connected for supplying current over the subscriber's line to charge said telephone.

4. In a telephone exchange system, the combination of a subscriber's line, trunk lines, an automatic trunk-selecting switch, means by which said switch is controlled over the line, a spring jack allotted to said line, an operator's connecting cord provided with a plug adapted for insertion in said jack, said jack being normally disconnected from said subscriber's line, and means for automatically connecting the jack with said subscriber's line when a manual connection is made therewith.

5. In a telephone exchange system, the combination of a subscriber's line, trunk lines, an individual trunk-selecting switch for said subscriber's line, means by which the subscriber controls the said switch to select an idle trunk line, a plurality of automatic connector switches each provided

with a multiple terminal of said subscriber's line, a plurality of multiple jacks allotted to said line, said jacks being normally disconnected from said subscriber's line, and means for automatically connecting the jacks with said subscriber's line when a manual connection is made therewith.

6. In a telephone exchange system, the combination of a subscriber's line, trunk lines, an automatic trunk-selecting switch, normally accessible automatically from said line, means by which said switch is controlled over the line, a spring jack allotted to said line, an operator's connecting cord provided with a plug adapted for insertion in said jack, a second subscriber's line, multiple jacks allotted to said second subscriber's line, a visual call-signal allotted to said second subscriber's line, and an operator's connecting cord provided with a plug adapted for insertion in the answering jack of said second subscriber's line, all of said jacks mounted on the same board.

7. In a telephone exchange system, the combination of a subscriber's line, trunk lines, an automatic trunk-selecting switch, normally accessible automatically from said line, means for transmitting electrical impulses over said line to control the operations of said switch, an automatic connecting switch for making connection with said line, manual switchboard apparatus for making connection with said line, whereby said line may call automatically and be called either automatically or manually, a second subscriber's line, multiple jacks allotted to said second subscriber's line, a visual call-signal allotted to said second subscriber's line, and an operator's connecting cord provided with a plug adapted for insertion in the answering jack of said second subscriber's line, all of said jacks mounted on the same board.

8. In a telephone exchange system, the combination of a subscriber's line, trunk lines, an individual trunk-selecting switch for said subscriber's line, means by which the subscriber controls the said switch to select an idle trunk line, a plurality of automatic connector switches each provided with a multiple terminal of said subscriber's line, a plurality of multiple jacks allotted to said line, a second subscriber's line, multiple jacks allotted to said second subscriber's line, a visual call-signal allotted to said second subscriber's line, and an operator's connecting cord provided with a plug adapted for insertion in the answering jack of said second subscriber's line, all of said jacks mounted on the same board.

9. In a telephone exchange system, the combination of a subscriber's line, trunk lines, an automatic trunk-selecting switch, means by which said switch is controlled over the line, a spring jack allotted to said

line, an operator's connecting cord provided with a plug adapted for insertion in said jack, a second subscriber's line, multiple jacks allotted to said second subscriber's line, a visual call-signal allotted to said second subscriber's line, an operator's connecting cord provided with a plug adapted for insertion in the answering jack of said second subscriber's line, all of said jacks mounted on the same board, a third subscriber's line, jacks for said third subscriber's line, a visual call-signal for said third subscriber's line, and means including a trunking operator's cord and plug for establishing 5 trunk connection from either the first or the second subscriber's line to the said third subscriber's line, the jacks of the said first and second subscribers' lines being mounted on the same board, and the jacks of the third subscriber's line being mounted on another board.

10. In a telephone exchange system, the combination of a subscriber's line, trunk lines, an automatic trunk-selecting switch, means for transmitting electrical impulses over said line to control the operations of said switch, an automatic connecting switch for making connection with said line, manual switchboard apparatus for making connection with said line, whereby said line may call automatically and be called either automatically or manually, a second subscriber's line, multiple jacks allotted to said second subscriber's line, a visual call-signal allotted to said second subscriber's line, an operator's connecting cord provided with a plug adapted for insertion in the answering jack of said second subscriber's line, all of said jacks mounted on the same board, a third subscriber's line, jacks for said third subscriber's line, a visual call-signal for said third subscriber's line, and means including a trunking operator's cord and plug for establishing 15 trunk connection from either the first or the second subscriber's line to the said third subscriber's line, the jacks of the said first and second subscribers' lines being mounted on the same board, and the jacks of the third subscriber's line being mounted on another board.

12. In a telephone exchange system, the combination of a subscriber's line, an automatic electrically-propelled and step-by-step-actuated switch, means by which the subscriber operates the switch over the line in automatically establishing connection with some other line, a spring jack allotted to said line, an operator's connecting cord provided with a plug adapted for insertion in said jack, a second subscriber's line, multiple jacks allotted to said second subscriber's line, a visual call-signal allotted to said second subscriber's line, an operator's connecting cord provided with a plug adapted for insertion in the answering jack of said second subscriber's line, all of said jacks mounted on the same board, a third subscriber's line, jacks for said third subscriber's line, a visual call-signal for said third subscriber's line, and means including a trunking operator's cord and plug for establishing 20 trunk connection from either the first or the second subscriber's line to the said third subscriber's line, the jacks of the said first and second subscribers' lines being mounted on the same board, and the jacks of the third subscriber's line being mounted on another board.

13. A telephone exchange system comprising a multiple switchboard, automatic and manual subscribers' lines terminating on said board, automatic switches controlled by the automatic subscribers and normally accessible automatically from said lines, multiple jacks for the automatic and manual lines, line signals for the manual lines, supervisory apparatus for the manual lines, automatic switch terminals for the automatic and manual lines, and operators' cords and plugs for connecting the jacks of calling manual lines with the jacks of called automatic or manual lines.

14. In a telephone exchange system, the combination of a multiple switchboard, automatic and manual subscribers' lines terminating on said board, automatic switches controlled by the automatic subscribers, multiple jacks for the automatic and manual lines, line signals for the manual lines, supervisory apparatus for the manual lines, automatic switch terminals for the automatic and manual lines, operators' cords and plugs for connecting the jacks of calling manual lines with the jacks of called automatic or manual lines.

manual lines with the jacks of called automatic or manual lines, said jacks normally disconnected from the automatic and manual lines, and relays controlling the normally open connections between the jacks and lines.

15. In a telephone exchange system, the combination of a multiple switchboard, automatic and manual subscribers' lines terminating on said board, automatic switches controlled by the automatic subscribers, multiple jacks for the automatic and manual lines, line signals for the manual lines, supervisory apparatus for the manual lines, 10 automatic switch terminals for the automatic and manual lines, operators' cords and plugs for connecting the jacks of calling manual lines with the jacks of called automatic or manual lines, said automatic switch terminals being permanently connected with the automatic lines, but normally disconnected from the manual lines.

16. In a telephone exchange system, the combination of a multiple switchboard, automatic and manual subscribers' lines terminating on said board, automatic switches controlled by the automatic subscribers, multiple jacks for the automatic and manual lines, line signals for the manual lines, supervisory apparatus for the manual lines, 25 automatic switch terminals for the automatic and manual lines, operators' cords and plugs for connecting the jacks of calling manual lines with the jacks of called automatic or manual lines, and suitable instrumentalities for supplying talking current through the jacks and automatic switch terminals to the subscribers' lines.

17. A telephone exchange system comprising 40 a subscriber's line, a pair of line relays normally bridged across said line, an automatic switch mechanism controlled by said line relays, a subscriber's calling device for controlling said relays, a bridge-cut-off relay, instrumentalities for energizing said bridge-cut-off relay while the subscriber's line is calling or called, a spring jack normally disconnected from said subscriber's line, and means for connecting the jack with the line when the bridge-cut-off relay is energized.

18. In a telephone exchange system, the combination of a subscriber's line, a pair of line relays normally bridged across said line, 55 an automatic switch mechanism controlled by said line relays, a subscriber's calling device for controlling said relays, a bridge-cut-off relay, instrumentalities for energizing said bridge-cut-off relay while the subscriber's line is calling or called, a spring jack normally disconnected from said subscriber's line, means for connecting the jack with the line when the bridge-cut-off relay is energized, a connector bank terminal allotted to said subscriber's line, and suitable

instrumentalities for supplying talking current through either the jack or the connector bank terminal to the subscriber's line.

19. In a telephone exchange system, the combination of a subscriber's line, a pair of line relays normally bridged across said line, an automatic switch mechanism controlled by said line relays, a subscriber's calling device for controlling said relays, a bridge-cut-off relay, instrumentalities for energizing said bridge-cut-off relay while the subscriber's line is calling or called, a spring jack normally disconnected from said subscriber's line, means for connecting the jack with the line when the bridge-cut-off relay is energized, a common battery, a connector bank terminal allotted to said line, a pair of connector relay coils for feeding talking current through the said bank terminal to the subscriber's line, and means by which talking current is also supplied to the line when manual connection is established therewith through the medium of said jack. 75

20. A telephone exchange system comprising trunk lines, an automatic trunk selector, a called telephone line, a private normal relay for said selector, and means by which the energizing of said relay establishes a guarding potential to prevent seizure of said called line by other subscribers. 80

21. A telephone exchange system comprising a selector, a line, a bridge across said line, a line-switching and bridge-cut-off relay, a private normal relay, a called telephone line, a spring jack for said called telephone line, and means operated by the private normal relay for causing the bridge-cut-off relay to open said bridge and close the line connection through to the said spring jack. 95

22. A telephone exchange system comprising trunk lines, an automatic trunk selector, a private normal relay for said selector, a private normal conductor, and a manual switchboard provided with means by which the operator controls the said relay to establish a guarding potential over the private normal conductor, for the purpose set forth. 105

23. A telephone exchange system comprising automatic subscribers' lines, trunk lines, an automatic trunk selector, a line, a line-switching relay for said selector, a multiple jack, a manual switchboard operator's cord circuit, a manual subscriber's line, a side switch for said selector, and means controlled or operated by the relay for connecting automatic subscribers' lines with the multiple jack, with the manual operator's cord circuit, and with the manual subscriber's line. 115

24. A telephone exchange system comprising automatic and manual subscribers' telephone lines, automatic switches for making connections between lines, a manual oper- 120

operator's cord circuit for making connections between lines, and means for supplying talking current through the operator's cord circuit to an automatic subscriber's telephone line when the latter is called by a manual subscriber.

25. A telephone exchange system comprising automatic and manual subscribers' lines, automatic and manual switchboard apparatus for making connections between lines, said manual apparatus comprising a pair of supervisory relays, and means for supplying talking current through the windings of said relays to an automatic subscriber's line when the latter is called by a manual subscriber.

26. In a telephone exchange system, the combination of automatic subscribers' lines, automatic switches controlled by the automatic subscribers, multiple jacks for each subscriber's line, means for supplying talking current through the jacks to the lines, and means for supplying talking current through the automatic switches to the lines.

25 27. In a telephone exchange system, the combination of automatic subscribers' lines, automatic switches controlled by the subscribers, multiple jacks for each subscriber's line, operators' cords and plugs adapted to cooperate with said jacks in establishing connections with the lines, and suitable instrumentalities for supplying talking current over the lines to the subscribers' stations.

28. In a telephone exchange system, the combination of automatic subscribers' lines, automatic switches controlled by the automatic subscribers, normally disconnected multiple jacks for each subscriber's line, means for supplying talking current through the jacks to the lines, and means for supplying talking current through the automatic switches to the lines.

29. In a telephone exchange system, the combination of automatic subscribers' lines, automatic switches controlled by the subscribers, normally disconnected multiple jacks for each subscriber's line, operator's cords and plugs adapted to cooperate with said jacks in establishing connections with the lines, and suitable instrumentalities for supplying talking current over the lines to the subscribers' stations.

30. A telephone exchange system comprising automatic and manual subscribers' lines, automatic switches controlled by the automatic subscribers, manual switchboard apparatus for making connections between lines, a source of current by which a manual switchboard operator tests an automatic line when the latter is called by another automatic line, and another source of current by which the manual switchboard operator tests an automatic line when the latter is called by a manual subscriber.

31. A telephone exchange system comprising a calling telephone line, a trunk line provided at one end with a repeater and at the other end with a trunking operator's cord circuit, an automatic switch by which the calling subscriber establishes connection with the repeater, said repeater provided with means for use in releasing the automatic switch, and said cord circuit provided with supervisory apparatus controlled by a calling subscriber through the medium of said repeater.

32. A telephone exchange system comprising a calling telephone line, a trunk line provided with a repeater, an automatic switch by which the calling subscriber makes connection with the said repeater, and a manual switchboard in which the said trunk line terminates, said switchboard provided with supervisory apparatus controlled by the calling subscriber through the medium of said repeater.

33. A telephone exchange system comprising a trunk line provided with a repeater, an automatic switch for making connection with the repeater, a spring jack allotted to said trunk line, a trunking operator's cord circuit also allotted to said trunk line, a cord and plug adapted for insertion in said jack, and supervisory apparatus adapted to be controlled through the medium of said repeater, said repeater provided with means for use in releasing said automatic switch.

34. A telephone exchange system comprising a calling subscriber's line, a repeater, an automatic switch by which the subscriber establishes connection with the repeater, a trunk line leading from the repeater, a trunking operator's cord circuit provided with a plug, and repeater coils for inductively connecting said plug and cord circuit with said trunk line.

35. A telephone exchange system comprising a repeater, an automatic switch for making connection with the repeater, a trunk line leading from the repeater, a trunking operator's cord circuit in which the trunk line terminates, means controlled by the repeater for signaling the trunking operator, a spring jack allotted to said trunk line, an operator's cord and plug adapted for insertion in said jack, and means by which the operator at one cord circuit may communicate with the operator at the other cord circuit.

36. A telephone exchange system comprising a repeater, an automatic switch for making connection with the repeater, a trunk line leading from the repeater, a trunking operator's cord circuit in which the trunk line terminates, means controlled by the repeater for signaling the trunking operator, a spring jack allotted to said trunk line, an operator's cord and plug adapted for inser-

tion in said jack, and an operator's private order wire connecting one cord circuit with the other.

37. A telephone exchange system comprising an automatic subscriber's line, an automatic switch controlled by the automatic subscriber, a trunk line leading from said automatic switch, multiple jacks allotted to said trunk line, cords and plugs adapted to cooperate with said multiple jacks in trunking over said trunk line, and means for establishing a guarding or testing potential at the idle multiple jacks when a cord and plug are inserted in a jack.

15 38. A telephone exchange system comprising a trunk line, subscriber-controlled automatic means for trunking over said line, and switchboard-operator-controlled manual means for trunking over the line in the 20 same direction.

25 39. A telephone exchange system comprising a trunk line, subscriber-controlled automatic means for trunking over said line in one direction, manual switchboard apparatus for trunking over said line in the same direction, and manual switchboard apparatus for trunking over said line in the opposite direction.

30 40. A telephone exchange system comprising automatic subscribers' lines, manual subscribers' lines, automatic switches normally accessible automatically from said lines by which an automatic subscriber calls another automatic subscriber, or by which an automatic subscriber calls a manual subscriber, manual switchboard apparatus by which a manual subscriber calls another manual subscriber, or by which a manual subscriber calls an automatic subscriber, and means for 40 supplying talking current to the automatic and manual subscribers' lines.

45 41. In a telephone exchange system, the combination of an automatic subscriber's line, automatic switches controlled by the automatic subscriber, manual subscribers' lines, manual switchboard apparatus for said manual lines, means for establishing a guarding potential for the automatic line when the subscriber thereof calls, means for 50 establishing a guarding potential for the same line when the subscriber thereof is called by another automatic subscriber, and means for establishing a guarding potential for the said automatic line when the same is 55 called by a manual subscriber, together with common battery means for supplying talking current to the automatic and manual telephone lines.

60 42. In a telephone exchange system, the combination of automatic subscribers' lines, manual subscribers' lines, trunk lines, individual switches by which the automatic subscribers automatically select idle trunk lines, spring jacks normally disconnected from the 65 automatic lines, said individual switches

provided with means for closing connection between said jacks and the automatic lines, spring jacks for the manual subscribers' lines, operator-controlled means for establishing connection between the manual lines and their said jacks, connector bank terminals allotted to the manual lines and adapted for use when an automatic subscriber calls a manual subscriber, and cords and plugs adapted for insertion in said jacks.

75 43. In a telephone exchange system, the combination of automatic subscribers' lines, manual subscribers' lines, trunk lines, individual switches by which the automatic subscribers automatically select idle trunk lines, spring jacks normally disconnected from the automatic lines, said individual switches provided with means for closing connection between said jacks and the automatic lines, spring jacks for the manual subscribers' lines, operator-controlled means for establishing connection between the manual lines and their said jacks, connector bank terminals allotted to the manual lines and adapted for use when an automatic subscriber calls a manual subscriber, and cords and plugs adapted for insertion in said jacks, together with common battery means for supplying talking current to both the automatic and manual lines.

80 44. The combination of subscribers' automatic individual trunking switches, connector-switches, a manual switchboard apparatus comprising two groups of multiple jacks, one group connected in multiple with the trunk terminals of the individual switches, and the other group connected in multiple with the terminals of the connector-switches.

85 45. The combination of subscribers' automatic individual trunking switches, connector-switches, a manual switchboard apparatus comprising two groups of multiple jacks, one group connected in multiple with the trunk terminals of the individual switches, and the other group connected in multiple with the terminals of the connector-switches, and a line leading from each set of multiple jacks in each group.

90 46. The combination of subscribers' automatic individual trunking switches, connector-switches, a manual switchboard apparatus comprising two groups of multiple jacks, one group connected in multiple with the trunk terminals of the individual switches, and the other group connected in multiple with the terminals of the connector-switches, together with centralized common battery means for supplying talking current to the subscribers' stations.

95 47. The combination of subscribers' automatic individual trunking switches, connector-switches, a manual switchboard apparatus comprising two groups of multiple jacks, one group connected in multiple with the trunk terminals of the individual

switches, and the other group connected in multiple with the terminals of the connector-switches, and a line leading from each set of multiple jacks in each group, together with centralized common battery means for supplying talking current to the subscribers' stations.

48. In a telephone exchange system, means for trunking between exchanges, comprising 10 a two-way trunk line, automatic means for trunking over said line in one direction, manual means for trunking over said line in an opposite direction and a common battery for supplying talking current.

49. In a telephone exchange system, the combination of a two-way trunk line, an automatic switch for establishing connection with one end of said trunk line when the latter is to be used for trunking in one direction, and common battery manual switchboard apparatus for trunking over said line in an opposite direction.

50. In a telephone exchange system, the combination of a two-way trunk line, an automatic switch, a manual switchboard for use in conjunction with said automatic switch when the line is to be used for trunking in one direction, and another manual switchboard adapted for use in conjunction with said first-mentioned switchboard when the line is to be used for trunking in an opposite direction.

51. In a telephone exchange system, the combination of a two-way trunk line, an automatic switch adapted to make connection with one end of said trunk line, a manual switchboard at the other end of said trunk line, adapted to cooperate with said automatic switch when the line is to be used for trunking in one direction, and another manual switchboard adapted to cooperate with said first-mentioned manual switchboard when the line is to be used for manually trunking in either direction.

52. A telephone exchange system having provisions for making both purely manual and mixed automatic and manual connections between subscribers' stations, and a manual switchboard operator's supervisory apparatus common to both kinds of connections.

53. In a telephone exchange system, the combination of a two-way trunk line, an automatic first-selector for use in trunking over said line in one direction, a spring jack and operator's cord and plug for use in trunking over said line in the same direction, and a common battery for supplying talking current.

54. In a telephone exchange system, the combination of a two-way trunk line, an automatic first-selector for use in trunking over said line in one direction, a spring jack and operator's cord and plug for use in trunking over said line in the opposite

direction, and a common battery for supplying talking current.

55. A mixed manual and automatic telephone exchange system, with provisions for intercommunication between the manual and automatic subscribers thereof, comprising lines having both jacks and automatic switches, other lines having jacks only, and means at the exchange for supplying talking current to all of said lines, substantially as described.

56. In a telephone exchange system, the combination of a telephone line, a spring jack for said line, an individual automatic trunking switch for said line, a connector having a terminal of said line, a common battery circuit including the line and jack, a second common battery circuit including the line and connector terminal, and a third battery circuit including the line and trunking switch.

57. In a telephone system, a subscriber's line, means for extending connection automatically from said line to some other line, means for semi-automatically extending a trunk connection from said subscriber's line to some other line, and common battery means for supplying current over said subscriber's line to the substation thereof for talking purposes.

58. In a telephone system, a subscriber's line, means for extending connection automatically from said line to some other line, means including a repeater for semi-automatically extending connection from said line to some other line, and means for supplying current through windings of said repeater to the said calling line for talking purposes.

59. In a telephone system, a calling telephone line, means for automatically trunking said line into connection with some other line, means for semi-automatically trunking said line into connection with some other line, means for supplying current over substantially the entire automatic trunking connection to the calling line for talking purposes, and connections whereby the talking current is supplied to the calling line over only a short portion of the semi-automatic trunking connection.

60. In a telephone system, a trunk terminating at one end in a cord and plug, means having one motion to select groups and another motion to connect with a line in any selected group responsive to a calling subscriber for seizing the other end of said trunk, and a signal at the cord responsive to the seizure of the other end of the trunk.

61. In a telephone system, a trunk, a repeater in the trunk, a cord and plug for one end of the trunk, a signal at the cord responsive to the said repeater, and means for automatically seizing the other end of said trunk.

62. In a telephone system, a cord and plug, a trunk, means for connecting a calling subscriber with said trunk, a repeater in the trunk responsive to a calling subscriber, means for automatically extending a connection from said trunk to the cord, and a signal at the cord responsive to said repeater. 70
63. In a telephone system, a trunk, a cord and plug for one end of said trunk, a jack for the same end thereof, means having vertical and rotary switching motions controlled from a calling substation to seize the other end of said trunk, and a common battery for supplying talking current to said substation. 75
64. In a telephone system, manual and automatic multiple line terminals, an automatic line, a manual line the two sides of which are normally disconnected from said multiple terminals of different kinds, and means for manually connecting a calling automatic line with said line. 80
65. In a telephone system, manual and automatic multiple line terminals, an automatic line, a subscriber's manual line the two sides of which are normally disconnected from said multiple terminals of different kinds, and means for manually connecting a calling automatic line with said line. 85
66. In a telephone system, a line, multiple line terminals of different kinds normally disconnected from said line, means controlled by an operator for connecting the line with a plurality of multiple terminals of different kinds, calling automatic lines, and means for manually connecting a calling automatic line with said line. 90
67. In a telephone system, a trunk, a cord and plug for one end of said trunk, a jack individual to the same end thereof, and an automatic switch having a progressively movable wiper for seizing the other end of said trunk. 105
68. A combined manual and automatic telephone system, comprising a plurality of telephone lines, part provided only with manual and part only with automatic substation equipment, manually operated link-circuit apparatus for establishing connection for conversational purposes between a manually equipped calling line and any other desired line and electrically actuated link-circuit apparatus for automatically establishing connection for conversational purposes between an automatically equipped calling line and any other desired line. 110
69. A combined manual and automatic telephone system comprising a plurality of telephone lines, part provided only with manual and part with automatic substation equipment, exchange talking and operating battery supply for said system; manually operated link-circuit apparatus for establishing connection for conversational purposes between a manually equipped calling line and any other desired line. 120
70. A combined manual and automatic telephone system comprising a plurality of telephone lines, part provided only with manual and part with automatic substation equipment, manually operated link-circuit apparatus for establishing connection for conversational purposes between a manually equipped calling line and any other desired line. 125
71. A combined manual and automatic telephone system comprising a plurality of telephone lines, part provided with manual and part with automatic substation equipment, manually operated link-circuit apparatus for establishing connection for conversational purposes between a manually equipped calling line and any other desired line. 130

- one of said lines, a central source for supplying talking current to the manually equipped substation thus connected, and common battery automatic switch mechanism associated with the lines having said automatic substation equipment and controlled by said equipment to extend the circuit of said lines. 70
74. A combined manual and automatic telephone system comprising a plurality of telephone lines, part provided with manual and part with automatic substation equipment, manually operated link-circuit apparatus for establishing connection for conversational purposes between a manually equipped calling line and any other desired one of said lines, a central source for supplying talking current to the substations of connected lines, means for indicating to the operator the busy condition of any called line sought to be manually connected and automatic switch mechanism associated with the lines having said automatic substation equipment and controlled by said equipment to extend the circuits of said lines. 80
75. A combined manual and automatic telephone system comprising a plurality of telephone lines, part provided with manual and part with automatic substation equipment, manually operated link-circuit apparatus for establishing connection for conversational purposes between a manually equipped calling line and any other desired one of said lines, electrically actuated link-circuit apparatus for automatically establishing connection for conversational purposes between an automatically equipped calling line and any other desired one of said lines, a central source for supplying talking current to the substations of connected lines, and means under the control of a called party for controlling the supply of said talking current to a calling substation provided with automatic equipment. 90
76. A combined manual and automatic telephone system comprising a plurality of telephone lines, part provided with manual and part with automatic substation equipment, electrically actuated link circuit apparatus for automatically establishing a connection for conversational purposes between an automatically equipped calling line and any other of said lines, link circuits for connecting a manually equipped calling line and any other desired one of said lines, and a central source for supplying talking current to the substations of the connected lines. 100
77. A combined manual and automatic telephone system comprising a plurality of telephone lines, part provided with manual and part provided with automatic substation equipment, electrically actuated link circuit apparatus for automatically establishing a connection for conversational purposes between an automatically equipped calling line and a manually equipped called line, link circuits for establishing connection between a manually equipped calling line and an automatically equipped called line, and a central source for supplying talking current to the substations thus connected. 110
78. A combined manual and automatic telephone system comprising telephone lines, part provided only with manual, part only with automatic substation equipment, common battery manually operated link circuit apparatus for establishing connection for conversational purposes between a manually equipped calling line and any other desired one of said lines, and common battery automatic switch mechanism associated with the lines having said automatic substation equipment and controlled by said equipment to extend the circuits of said lines. 120
79. A combined manual and automatic telephone system, comprising automatic and manually equipped substation telephone lines, manually operated link circuit apparatus for establishing connection for conversational purposes between a manually equipped calling line and any other desired one of said lines, automatic link circuit apparatus for establishing connection for conversational purposes between an automatically equipped calling line and any other desired one of said lines, and exchange talking and operating battery supply for said system. 130
80. A combined manual and automatic telephone system comprising manually and automatically equipped substations, electrically actuated link circuit apparatus for automatically completing connection for conversational purposes between an automatically equipped calling line and a manually equipped called line, means controlled from a connected substation for restoring the interconnecting apparatus to normal at the end of conversation, operator's means for extending the circuit of manual lines to any other desired one of said lines, and exchange talking and operating battery supply for said system. 140
81. In a telephone system, an automatic subscriber controlled switch, a manual jack, a trunk line accessible to said switch and extending to said jack, said trunk line comprising two inductively connected sections, a relay energized over a conductor of one section when a plug is inserted in said jack, and a circuit controlled by said relay for making the other section busy to said switch. 150
82. In a telephone system, an automatic to manual trunk, a manual connective terminal for said trunk at the manual end, bank contacts in which said trunk terminates at the automatic end, an automatic switch directly controlled by a calling subscriber for connecting his line with said bank contacts, and a call signal at the man-

ual end of said trunk operated responsive to the establishment of the connection.

83. In a telephone system, an automatic to manual trunk, a manual connective terminal for said trunk at the manual end, bank contacts, in which said trunk terminates at the automatic end, an automatic switch directly controlled by a calling subscriber for connecting his line with said bank contacts, a call signal at the manual end of said trunk, and a signal controlling relay energized independent of subscriber control when the connection is established.

84. In a telephone system, an automatic to manual trunk, a manual connective terminal for said trunk at the manual end, bank contacts in which said trunk terminates at the automatic end, an automatic switch directly controlled by a calling subscriber for connecting his line with said bank contacts, and inductive windings individual to said trunk for feeding talking current to the transmitter at the calling station.

85. In a telephone system, an automatic to manual trunk, a manual connective terminal for said trunk at the manual end, bank contacts in which said trunk terminates at the automatic end, an automatic switch directly controlled by a calling subscriber for connecting his line with said bank contacts, a central source of current, and circuit connections for automatically supplying talking current from said source to the transmitter at the calling station as soon as the said connection is established.

86. In a telephone system, an automatic to manual trunk, a manual connective terminal for said trunk at the manual end, bank contacts in which said trunk terminates at the automatic end, an automatic switch directly controlled by a calling subscriber for connecting his line with said bank contacts, a called line adapted to be connected with said trunk by means of said manual connective terminal, a central source of current, and circuit connections for automatically supplying talking current to the transmitter at the calling station before the trunk is connected with the called line.

87. In a telephone system, a subscriber's line, an automatic switch and a manual jack both individual to said line, a controlling line relay in said switch, a cut off relay, and contact springs on said relay for disconnecting said line relay from said line and for connecting said jack to said line.

88. In a telephone system, an automatic subscriber's line, an automatic switch for extending outgoing calls from said line, a second automatic line and a manual line, a set of normally connected normal conductors for receiving incoming calls from the second automatic line, and a set of normally disconnected normal conductors for receiving calls from the manual line.

89. In a mixed automatic and manual telephone system, an automatic subscriber's line, an automatic switch for extending calls from said line, and means for extending calls to said line comprising a three conductor branch for handling calls from other automatic lines and a two conductor branch for handling calls from manual lines.

90. In a mixed automatic and manual telephone system, an automatic subscriber's line, an automatic switch for extending calls from said line, means for extending calls to said line comprising a three conductor branch for handling calls from other automatic lines and a two conductor branch for handling calls from manual lines, and means for making said subscriber's line busy to all other calls when the same is engaged as a called line in a purely automatic or manual to automatic connection.

91. In a mixed automatic and manual telephone system, an automatic subscriber's line, an automatic switch for extending calls from said line comprising a three conductor branch for handling calls from other automatic lines and a two conductor branch for handling calls from manual lines, a test conductor included in said three conductor branch, and a relay energized over a talking conductor of said two conductor branch when said subscriber's line is called manually for placing a test potential on said test conductor.

92. In a mixed automatic and manual telephone system, an automatic subscriber's line, an automatic switch for extending outgoing calls from said line, means for extending calls to said line comprising a branch for calls from other automatic lines and a separate branch for calls from manual lines, a relay energized when said line is called manually, and a test circuit controlled by said relay for making said subscriber's line busy to incoming calls from automatic lines.

93. In a mixed automatic and manual telephone system, an automatic subscriber's line, an automatic switch for extending outgoing calls from said line, means for extending calls to said line comprising a branch for calls from other automatic lines and a separate branch for calls from manual lines, a relay energized when said line is called automatically, and a test circuit controlled by said relay for making said subscriber's line busy to incoming calls from manual lines.

94. In a mixed automatic and manual telephone system, an automatic subscriber's line, an automatic switch for extending outgoing calls from said line, means for extending calls to said line comprising a branch for calls from other automatic lines and a separate branch for calls from manual

- lines, a relay for making said subscriber's line busy to incoming automatic calls when the line is called from a manual line, and a second relay for making said subscriber's line busy to incoming manual calls when the line is called from an automatic line.
95. In a mixed automatic and manual telephone system, automatic subscribers' lines provided with automatic switching apparatus for extending outgoing calls, said lines being also provided with manual jacks, manual lines provided with jacks similar to the jacks of the automatic lines, and operator's double ended cord circuits for directly connecting any manual line with any automatic line or with any other manual line.
96. In a combined automatic and manual telephone system, automatic and manual lines provided with automatic and manual substation equipment, respectively, subscriber controlled automatic switching equipment for completing connections from an automatic line to the manual lines or to the other automatic lines, said switching equipment including final connector switches having access to the manual lines, and operator's cord circuits for extending connections from a manual line to the automatic lines or to the other manual lines.
97. In a combined automatic and manual telephone system, automatic and manual lines having automatic and manual substation equipment, respectively, automatic subscriber controlled connector switches having access to the automatic lines, other automatic subscriber controlled connector switches having access to the manual lines, and manual operator's connective apparatus having access to both kinds of lines.
98. In a telephone system, the combination with manual and automatic telephone lines, of connecting means at the central office for establishing either manual or automatic connections with either of said lines, the establishment of an automatic connection with either of said lines being adapted to place battery potential upon the test contacts of the manual connecting means and ground potential upon the test contacts of the automatic connecting means to indicate that the line is busy for both automatic and manual connections, and the establishment of a manual connection with either of said lines being adapted to indicate that the line is busy both for manual and automatic connections.
99. In a telephone system, the combination with a telephone line, of multiple jacks and multiple automatic connector contacts for said line, a cord circuit and a connector switch, a cut-off relay for the line, the establishment of a connection between either the cord circuit or the automatic connector switch and said line, being adapted to connect the grounded pole of battery with the private contacts of the connector switch multiple and the non-grounded pole of battery with the test contacts of the multiple jacks.
100. In a telephone system, the combination with a telephone line, of a cut-off relay for the line, a pair of conductors over which a conversational circuit is adapted to be completed when said line is called, and a third conductor independent of the talking circuit, said cut-off relay adapted to be actuated either over one of said talking conductors or other said third conductor.

Signed by me at Chicago, Cook County, Illinois, this 15th day of October, 1906.

TALBOT G. MARTIN.
